ABSTRACT

Rotary engine apparatus of the internal combustion type in which the reciprocable displacements of the respective pistons within the cylinders therefor impart rotatory motion to a variety of engine components from which output torque is delivered to a power shaft. The rate at which the piston-cylinder structures fire is selectively variable at any engine operating speed so that the power delivered by the engine at any speed thereof can be specifically related to the contemporary value of the load on the engine. The stroke length of each reciprocable piston is also selectively variable for load-accommodating purposes; and the rotatory components of the apparatus may be used directly to drive an output power shaft selectively in opposite angular directions, thereby obviating the necessity of providing transmission mechanism for this purpose.

ROTARY ENGINE APPARATUS

RELATED APPLICATION

This application is a Continuation-In-Part of our copending application Ser. No. 856,244, filed Aug. 11, 1969, for AUTOMATICALLY CONTROLLED VARIABLE RAPID FIRE ROTARY ENGINE and now abandoned.

This invention relates to engine apparatus and, more particularly, to rotary engine apparatus of the internal combustion type having utility in substantially all environments in which engine apparatus is now used including use thereof as a power plant for automotive vehicles.

Although the internal combustion engine has reached a high degree of refinement in terms of its reliability and ease of use, both in the low-pressure carburetor and high-pressure diesel forms thereof, the ratio of engine weight to output horsepower remains quite high and the thermodynamic efficiency of such engines remains relatively low. As respects the former, the engines presently used in automotive and other vehicles are generally very massive and represent a substantial portion of the gross weight of each such vehicle; and as respects the latter, the results of low engine efficiency are evident in the atmospheric environment which is rapidly increasing in the concentration it contains of those pollutants that constitute by-products of the combustion of hydrocarbon fuels in internal combustion engines. In this same reference, it may be observed that the tremendous total consumption of hydrocarbon fuels in the United States in vehicles of various types, and which total consumption could be reduced by improved engine efficiency, has very seriously depleted known fuel reserves to the point that exhaustion thereof is rapidly approaching.

Further as respects the adverse effects of low efficiency, the conventional internal combustion engine produces more pollutants at idle and low speed operation than at average to higher operating speeds particularly because of the too rich fuel-to-air admixtures at such low speed operating conditions and also because of the inertial differences in the flow characteristics of liquid fuels and the gaseous fluids for admixture therewith and which differences are more significant at low operating speeds. Accordingly, such conventional engines produce more pollutants at and about the various population centers where stop and go driving and low speeds are mandatory, and which centers are otherwise and already adversely affected by environmental pollution simply because of the concentration of vehicles thereto.

In view of the foregoing, a general object of the present invention is to provide improved internal combustion engine apparatus — improved in the sense of using fuel more efficiently, of having a superior weight-to-horsepower ratio than conventional engines, and of being mechanically simplified at least in terms of the overall power train comprising the same which connects with the drive shaft of an automotive vehicle or other power shaft to be driven by the engine apparatus at varying angular velocities and sometimes selectively in opposite angular directions.

Another object of the invention is in the provision of an improved engine apparatus of the character described in which the power developed and delivered

thereby can be accurately tailored to satisfy the requirements of the contemporary magnitude of the load imposed thereon; and in which such accurate adjustment of the engine output is effected by reducing the firing rate of the engine without changing the output velocity thereof, by reducing the length of the stroke of each piston within the cylinder therefor, or by a combination of these two factors.

Still another object is that of providing an improved engine apparatus of the type set forth in which production and delivery of output torque is maximized by increasing the length of the lever arm through which the linear force development attributable to the reciprocating pistons of the engine is converted into angular force or torque, and by utilizing the inertia of the piston-cylinder structures and components operationally associated therewith as a part of the angular momentum characterizing the rotational components of the engine apparatus from which output torque is developed.

A further object is to provide an exceedingly versatile engine apparatus that obviates the requirement for a transmission in an automotive vehicle for the purpose of changing gear ratios in forward drive in accordance with load demands (e.g., acceleration, traversal of inclines, etc.), and of shifting between forward and reverse drive conditions; the engine apparatus being operative to accommodate rapid change from forward to reverse drive (and vice versa), thereby enabling the engine apparatus to be used for effective braking of a vehicle in addition to its being a reversible prime mover therefor.

Additional objects and advantages of the invention, especially as concerns particular features and characteristics thereof, will become apparent as the specification continues.

Briefly summarizing engine apparatus embodying the present invention, it may be said to be an internal combustion engine of either carburetion-ignition or diesel type, and of rotatory composition in which the reciprocable displacements of the various pistons within the cylinders thereof impart rotary motion to a plurality of rotatable components such as the main drive shaft and a casing component each of which is adapted to be coupled to an output power shaft so as to deliver torque thereto. The piston-cylinder structures are angularly disposed with respect to the axis of rotation of the engine, and they are radially spaced thereabout so that the linear forces developed thereby are applied between such main shaft and casing component via a relatively long lever arm to enhance the magnitude of the linear forces. The piston-cylinder structures are carried by one of the rotatory components of the engine and thereby contribute their inertia thereto. Adjustment structure is included in the engine apparatus for selectively changing the rate at which each piston-cylinder structure fires and also for changing the length of the reciprocable displacement of each piston within the cylinder therefor. The rotatory components of the engine apparatus may be selectively connected with an output power shaft and are able to rotate the same selectively in either angular direction.

An embodiment of the invention is illustrated in the accompanying drawings, in which:

FIG. 1 is essentially a schematic representation of engine apparatus embodying the present invention;

FIG. 2 is a broken perspective view of an end portion of the engine apparatus;

FIG. 3 is a transverse sectional view taken through the center of one of the combustion assemblies of the apparatus;

FIG. 4 is a bottom plan view of the combustion assembly shown in FIG. 3 with the circumferential cover thereof partially removed;

FIG. 5 is a broken perspective view of one of the pistons comprising a part of the combustion assembly shown in FIGS. 3 and 4;

FIG. 5A is a fragmentary view of the lower end portion of the valve lifter rod shown in FIG. 5;

FIG. 6 is a broken vertical sectional view through a portion of a piston illustrated in FIG. 5;

FIG. 10 is a transverse sectional view taken along the line 10—10 of FIGS. 8 and 9;

FIG. 11 is a graph depicting the cooperative relationship of the cam and cam followers plotted against time;

FIG. 12 is a vertical sectional view similar to FIG. 8 but illustrating the cam assembly shown therein in a different operating condition;

FIG. 13 is a longitudinal sectional view through the compressor assembly of the engine apparatus;

FIG. 14 is a transverse sectional view taken along the line 14—14 of FIG. 13;

FIG. 15 is a transverse sectional view taken along the line 15—15 of FIG. 13;

FIG. 16 is a broken longitudinal sectional view showing the power output end portion of the engine apparatus;

FIG. 17 is a simplified perspective view, somewhat diagrammatic, illustrating the water cooling and exhaust gas flow systems of the engine apparatus;

FIG. 18 is a schematic flow diagram of the air supply, exhaust gas, and water cooling systems of the engine apparatus;

FIG. 19 is a perspective view of a modified propulsion turbine; and

FIG. 20 is a schematic diagram of the control system of the engine apparatus generally indicating flow connections, but eliminating essentially all of the flow regulator and control devices.

GENERAL DESCRIPTION

Engine apparatus embodying the present invention will be described in terms of its general mechanical composition and functional characteristics prior to describing the various mechanical components in detail, and as respects such general description, reference will be made in particular to FIG. 1 which is essentially a schematic representation of the engine apparatus.

Generally stated, the engine apparatus constitutes a rotary engine of the internal combustion type in which the reciprocable displacements of the respective pistons within the cylinders therefor impart rotatory motion to a plurality of the engine components, usually

including the piston-cylinder structures and supports therefor which are angularly displaced or rotated. In the case of the particular embodiment of the engine apparatus being considered, the outer housing thereof is fixed or stationary and both an inner casing (sometimes referred to as a "cam track casing") and a main center shaft of the engine rotated and output power taken from one or the other. However, in other embodiments of the invention, the main shaft can be constrained in a stationary condition and the outer housing rotatably driven in which event it will be selectively coupled to a power output shaft to drive the same.

Also, the engine apparatus depicted in FIG. 1 in essence comprises two engines arranged structurally in back-to-back relationship and in functional parallelism. The two individual engine assemblies are substantially identical and, for this reason, the same numerals are used to denote respectively corresponding components and elements of these two assemblies except that the primed form is used in association with one of the two assemblies in order to differentiate therebetween. It should be noted, however, that it is not essential that any particular engine apparatus comprise two engine assemblies, and in environments in which less output horsepower is desired, only one such assembly need be used. Similarly, more than two assemblies can be employed in instances in which greater output power is required. In this same reference, as will become apparent hereinafter, each of the combustion assemblies comprises three piston-cylinder structures (not shown in FIG. 1) but it should be understood that a greater or lesser number of such structures can be employed in accordance with the requirements of any particular use or environment for the engine apparatus.

The engine apparatus generally illustrated in FIG. 1 is denoted in its entirety with the numeral 20, and it includes an outer housing 21 fixedly secured by means (not shown) to the chassis or frame structure of a vehicle or other mechanism with which the engine is used. Extending coaxially through the housing 21 and journaled for relative rotation with respect thereto in bearing structures 22 and 23 respectively located adjacent the opposite ends of the housing, the latter of which is a compound bearing structure also rotatably supporting a hollow transfer shaft 24, is a main shaft 25 adapted at certain times to mechanically drive a power output shaft 26 via the transfer shaft 24 and a gear train comprising meshing gears 27 and 28 keyed or otherwise constrained upon the respective shafts 24 and 26 so as to prevent relative rotation between each gear and its associated shaft. The power output shaft 26 is journaled for rotation with respect to the housing 21 in bearing structure 29, and in the case of the engine apparatus being used in an automotive vehicle, the power output shaft 26 will be connected directly or indirectly with the running gear of the vehicle so as to propel the same. For convenience of description, the shaft 25 is taken to be functionally the same as the shell 63, described hereinafter, so as to rotate therewith, and they are sometimes referred to hereinafter either individually or conjointly as the "main rotary." They may be structurally disassociated, however, with the shell 63 being the rotating component rather than the shaft 25.

Supported within the outer housing 21 and rotatable relative thereto is a cam casing or cam track casing 30

which is coaxially circumjacent the main shaft 25 and is also relatively rotatable with respect thereto. Disposed within the interior of the casing 30 at axially spaced locations adjacent the opposite end portions thereof are a pair of cam or cam track assemblies 31 and 31' fixedly secured to the casing so as to prevent relative rotation therebetween. Respectively associated with the cam assemblies 31 and 31' and disposed in adjacency therewith intermediate the same are a pair of combustion assemblies 32 and 32' each of which is constrained upon the main shaft 25 so as to rotate therewith. Each of the combustion assemblies 32 is equipped with one or more piston-cylinder structures effectively operative between the main shaft 25 and cam track casing 30 via the cam assembly 31 so as to effect relative rotation between the shaft and casing whenever the piston-cylinder structure is energized. In this sense, the cylinder 34 of each piston-cylinder structure is welded or otherwise rigidly affixed to the casing 35 of the combustion assembly so as to rotate with the shaft 25. The reciprocable piston 36 of each piston-cylinder structure is operative through linkage, indicated diagrammatically at 37, with a cam 38 forming a part of the cam assembly 31 so as to impart force thereto of varying magnitude as the piston reciprocates. As a result, the torque thereby developed between the combustion assembly 32 and main shaft 25 connected therewith and the cam assembly 31 and cam track casing 30 affixed thereto effects relative rotation between the main shaft and cam track casing.

Each piston-cylinder structure 36, 34 of the combustion assembly 32 is essentially the variable-volume combustion chamber of the engine apparatus, and each such structure is supplied with fuel and air in the proper ratios to support combustion which is initiated by the usual sparking device, although a diesel version of the specifically disclosed engine apparatus can be provided. Air for supporting combustion is supplied to the respective combustion assemblies 32 and 32' via compressor mechanisms or superchargers 39 and 39' which are rotary compressors and are supplied with atmospheric air through openings provided for this purposes in the outer housing 21, cam track casing 30, and an inner shell 63, as indicated by the directional arrows in FIG. 1. The compressed air outputs of the compressors 39 and 39' are delivered to the combustion assemblies 32 and 32' via a flow system (not shown) suggested by the directional lines extending therebetween.

The compressors 39 and 39' are driven by respectively associated turbines 40 and 40' by being keyed or otherwise affixed to a shaft 41 common to the turbines and compressors (separate shafts can be employed in respective association with the turbines 40 and 40' and their respective compressors). The turbines are exhaust gas turbines driven by the gaseous discharge from the respectively associated combustion assemblies 32 and 32'. This functional interconnection of each combustion assembly with its turbine is suggested by the flow lines in FIG. 1. The spent gases leaving the turbines 40 and 40' are exhausted to atmosphere after first being cooled by means not shown in FIG. 1 but which will be described in detail hereinafter. Accordingly, the exhaust gas discharge from each of the combustion assemblies is utilized in driving the compressors 39 and 39', thereby extracting from the exhaust gases energy

which otherwise would be dissipated to atmosphere as heat and pressure.

Adjacent one end thereof, the cam track casing 30 is provided with a transverse plate or annular flange 42 extending radially outwardly therefrom, and the shaft 25 is provided with a transversely extending mounting plate 43 keyed thereto. The flange projects into operative association with a brake mechanism 44 having components thereof fixedly associated with the stationary outer housing 21. Whenever the brake mechanism 44 is released, the casing 30 is free to rotate relative to the housing 21 and conversely, whenever the brake mechanism is energized, the casing is constrained against rotation relative to the housing. Operative between the main shaft 25 and cam track casing 30 adjacent the transverse flange 42 is a planetary gear train denoted with the numeral 45. The gear train 45 includes an outer ring gear 46 affixed to or otherwise provided by the casing 30 so as to rotate therewith, and it further includes a drive or sun gear 47 circumjacent the shaft 25 and journaled for rotation with respect thereto on the aforementioned bearing structure 22. Interposed between the outer and inner gears 46 and 47 are a plurality of sets of idler or planetary gears respectively denoted with the numerals 49 and 50, each pair of which meshingly engage each other and respectively engage the outer ring gear 46 and inner drive gear 47. As will be indicated more clearly hereinafter, there are three sets of gears 49 and 50 in the particular engine apparatus 20 and such sets of gears are angularly spaced from each other by 120°. Further each idler gear 49, 50 is rotatably supported by the plate 43 so as to orbit about the longitudinal axis of the shaft 25 upon rotation thereof; and the plate 43 and flange 42 are rotatably interrelated by bearing structure 43a.

Ordinarily, the drive gear 47 is free to rotate with respect to the main shaft 25 so that no driving interconnection is defined through the gear train 45 between the shaft and cam track casing 30. However, a driving interconnection between the shaft 25 and sun gear 47 can be selectively established by a hydraulic turbine or clutch mechanism 51 diagrammatically represented in FIG. 1 by a first set of plates 52 keyed or otherwise fixedly secured to an extension 53 of the gear 47 and by a second set of plates 54 rigid with the outer turbine shell which in turn is fixed to the stationary housing 21. It will be appreciated that when the clutch 51 is energized to resist free rotation of the sun gear 47 and the brake mechanism 44 is released, the cam track casing 30 will be driven by the shaft 25 in the same angular direction and at a relative velocity determined by the gear ratio defined by the gear train 45 and by the slippage or degree of coupling effected at any particular instant by the clutch 51.

In the particular embodiment of the invention being considered, the gear train 45 rotates the casing 30 at about 60% of the angular velocity of the shaft 25 when the clutch 51 is fully engaged. Accordingly, there is under these conditions a progressive change in the relative positions of the shaft 25 and casing 30 or, more particularly, between the combustion assembly 32 and the cam assembly 31. Such relative change in positions of the combustion assembly 32 and cam assembly 31 is used to control the rate of firing of the piston-cylinder structure 36, 34 in the manner described in detail

hereinafter. By way of example at this point, however, in the case in which the piston-cylinder structure fires four times during each rotation of the shaft 25 when the casing 30 and cam assembly 31 are fixed or stationary because of disengagement of the clutch 51 and energization of the brake mechanism 44, the piston-cylinder structure will fire an average of only 1.6 times during each rotation of the shaft 25 when the brake mechanism 44 is released and the clutch mechanism 51 fully actuated to drive the casing 30 and cam assembly 31 at approximately 60% of the angular velocity of the shaft 25. Less than complete engagement of the clutch 51 can be used to adjustably change the velocity differential between the shaft 25 and casing 30 toward the condition in which the casing is stationary, thereby increasing the rate of firing of the piston-cylinder structure toward the maximum four-cycle per revolution rate. It will be appreciated that the minimum velocity differential defined through the gear train 45 can be changed, by appropriate selection of the gear ratios, toward the idealized (but not theoretically practicable) differential of zero or a one-to-one ratio (with the brake 55 energized) in the same angular direction in which case the piston-cylinder structure would never fire.

A brake mechanism 55 is provided adjacent the clutch 51, and the brake mechanism is operative between the stationary housing 21 and sun gear 47. In this respect, the brake mechanism 55 is diagrammatically suggested by the provision of friction plates 56 and 57 respectively secured to the gear extension 53 and to the shell of the turbine 51. Force arrows are included to indicate the direction of movement of the plate 57 upon energization of the brake mechanism. The brake is useful in terminating rotation of the sun gear 47, as in slowing forward motion of an automotive vehicle in which the engine apparatus is used, and to completely constrain the sun gear against rotation and thereby cause the cam track casing 30 to rotate in the same angular direction as the shaft 25 at a fixed relative velocity defined by the gear train 45, as previously explained.

Adjacent its opposite end, the engine apparatus 20 is equipped with a pair of clutch mechanisms 58 and 59 selectively operative to rotate the power output shaft 26 (through the transfer shaft 24) in opposite angular directions, although the clutch 59 may drive the shaft in either direction in accordance with the direction of rotation of the cam track casing 30. In this respect, the clutch mechanism 58 may be used to impart forward motion to a vehicle with which the engine apparatus is used when such clutch is energized, and analogously, the clutch mechanism 59 is usually operative when energized to propel the vehicle in the opposite or rearward direction. However, when the cam track casing is rotated in the same direction as the shaft 25 because the gear train 45 is engaged, the clutch 59 will then impart forward motion to the vehicle. In the diagrammatic illustration of FIG. 1, the clutch mechanism 58 is depicted as having input and output sections 60 and 61 respectively connected with the main shaft 25 and with the transfer shaft 24. Accordingly, whenever the clutch mechanism 58 is energized so as to cause the output section 61 to be driven by the input section 60, the output shaft 26 is rotated in one angular direction to

propel an associated vehicle forwardly. Correspondingly, the rearward clutch mechanism 59 is provided with an input section 62 fixedly secured to the cam track casing 30 so as to be driven thereby, and it is also provided with an output section 64 fixedly secured to the transfer shaft 24 so as to drive the same. Therefore, whenever the cam track casing 30 is rotating, the forward clutch mechanism 58 is disengaged, and the rearward clutch mechanism 59 is energized, the output shaft 26 will be rotated in the angular direction corresponding to the direction of rotation of the casing 30.

It will be noted in FIG. 1 that a hydraulic turbine or clutch 51a, generally similar in structure and function to the aforementioned clutch 51, is located adjacent the output end of the engine and is operative between the shaft 25 and stationary housing 21. When energized, the clutch 51a constrains the shaft 25 against rotation (although some slippage is permitted), thereby causing the cam track casing 30 to rotate in a direction opposite that of the shaft 25, it being understood that the brakes 44 and 55 and clutch 51 are all de-energized. It may be observed at this point that the availability of oppositely rotatable components (i.e., the main shaft or rotary 25 and the cam track casing 30) and the various control mechanisms associated therewith enable the engine apparatus 20 to function not only as the prime mover for a vehicle, but also as the transmission therefor to obviate the usual requirement for a separate transmission.

An overall cycle of operation of the engine apparatus 20 as illustrated in FIG. 1 will now be described and as the starting condition, it will be assumed that the clutch mechanisms 58 and 59 are released or de-energized so that the engine apparatus is not drivingly connected to the output shaft 26, the brake mechanism 44 is energized to constrain the casing 30 against rotation, the clutch mechanism 51 is de-energized so that the sun gear 47 rotates freely with respect to the shaft 25, and the brake mechanism 55 is de-energized so that no inhibition to rotation of the gear 47 is defined thereby. The engine apparatus is started in a conventional manner by an electrically-driven automatic starter (not shown) releasably connectable with the shaft 25 so as to rotatably drive the same as part of the starting operation. Similarly, the piston-cylinder structures 36,34 are supplied with fuel and air, and the usual ignition system ignites a compressed combustible admixture of fuel and air within the cylinder 34 so as to energize the power stroke of the piston 36. Once operation is commenced, the piston-cylinder structures function in the ordinary manner of a two-cycle gasoline engine, and since the cam track casing 30 and cam assembly 31 are constrained against rotation, the force effectively developed between the cam assembly 31 and combustion assembly 32 upon reciprocal displacements of the piston 36 will cause the combustion assembly and main shaft to rotate relative both to the cam track casing 30 and to the outer housing 21 locked thereto by the brake mechanism 44.

The engine apparatus 20 will maintain this condition of idle operation until some change is made by an operator, such as energization of the forward clutch 58 to establish a driving connection between the main rotary and power output shaft 26 (via shaft 24) which will cause an associated vehicle to be propelled forwardly.

As the vehicle equipped with the engine apparatus increases in velocity, the load on the engine apparatus effectively diminishes and the requirement for delivery of power correspondingly decreases. As the requirement for the delivery of power to the output shaft 26 decreases, the engine apparatus is made to deliver less power by one or the other of two procedures or by combination thereof. First, the firing rate of the piston-cylinder structure 36,34 can be reduced by releasing the brake mechanism 44 and energizing the clutch mechanism 51 to cause the cam track casing 30 to be rotatably driven by the shaft 25 in the same angular direction via the planetary gear train 45. Secondly, and either in combination with the described rotation of the cam track casing 30 or as an alternative thereto, the stroke length of the piston 36 within its cylinder 34 can be decreased, thereby resulting in a smaller power development for each firing of the piston-cylinder structure, in a manner to be described in detail hereinafter. Thus, only that degree of power is delivered by the engine apparatus 20 which is required to accommodate the load on the output shaft 26.

Assume now the condition in which the vehicle has been stopped and the forward clutch mechanism 58 disengaged, the clutch mechanism 51 and brake 55 are both de-energized (if they are not already in a de-energized state), and the brake mechanism 44 is then de-energized so as to release the cam track casing 30 if it is not already in this state. The shaft 25 and cam track casing 30 may both be rotating, but their directions of rotation will be in opposite angular directions. If the hydraulic clutch 51a is then energized to constrain the shaft 25 against rotation, the cam track casing 30 will now be rotatably driven in a direction opposite to the direction of rotation of the shaft 25 whenever the latter is free to rotate. Accordingly, the driven or input section 62 of the rearward clutch 59 will be driven by the cam track casing 30 and whenever the clutch mechanism 59 is energized, the power output shaft 26 will be rotated in a direction causing the vehicle associated with the engine apparatus to be propelled rearwardly. If for any reason it should be necessary to continue driving the vehicle in reverse for any period of time, the output power delivered by the engine apparatus can be tailored to the requirements of the output load imposed on the shaft 26 by reducing the displacement of the piston 36 in a manner not illustrated in FIG. 1 but to be described hereinafter.

The vehicle may also be driven forwardly through the clutch 59 in those operating modes in which the cam track casing 30 is rotated in the same direction as the shaft 25 through the gear train 45. In this mode, the clutch 51a is de-energized so that the shaft 25 can rotate freely, the brake 44 is de-energized to permit the cam track casing 30 to rotate, and either the clutch 51 or brake 55 is energized to hold the sun gear 47. The cam track casing 30 will then be driven in the same direction as the shaft 25, and energization of the clutch 59 will therefore cause the power shaft 26 to propel the vehicle forwardly.

It should be noted that the engine apparatus 20 can be interchanged instantly from a forward to a reverse direction, or vice versa, with no danger of mechanically damaging or otherwise injuring the engine apparatus, thereby enabling it to be used to positively brake the

motion of an associated vehicle in either direction in which it may be propelled. For example, suppose that the rearward clutch 59 is disengaged and that the forward clutch is engaged and is propelling the vehicle forwardly at a relatively high velocity, if the rearward clutch 59 is engaged, the cam track casing 30 will tend to be rotated in the same direction as the shaft 25 because of the fluid coupling established between the input and output sections 62 and 64 of the rearward clutch since the output section 64 thereof is being driven by the transfer shaft 24, and this tendency will obtain irrespective of whether the cam track casing 30 is stationary or is being driven by the gear train 45, and irrespective of whether the forward clutch 58 is released concurrently with energization of the rearward clutch or is continued in its energized state. If the latter condition is continued, a simple braking action is effected.

If a complete reversal is desired, the forward clutch 58 will be de-energized, and as part of the reversing operation, the brake mechanisms 44 and 55 will be released and the turbine clutch 51 de-energized (if they are not already in the released and de-energized states) and the turbine clutch 51a energized so as to quickly reduce the angular velocity of the shaft 25 toward zero, whereupon all of the power development of the engine apparatus will be exerted through the cam assembly 31, cam track casing 30, and clutch mechanism 59 to reduce the rate of rotation of the transfer and output shafts 24 and 26 in one direction to zero and then to reverse the direction of rotation thereof. Thus, the engine apparatus 20 can be effectively utilized as a brake to stop movement of the vehicle in one direction and, if desired, reverse its direction of movement.

Similarly, the same braking action and rapid reversal can be used to switch the direction of movement of the vehicle from reverse to forward direction simply by de-energizing the clutch mechanism 59, energizing the clutch mechanism 58, de-energizing the turbine clutch 51a, and engaging the brake mechanism 44, (for complete reversal); or by simply energizing the forward clutch 58 and, if necessary, advantageously disengaging the gear train 45 and engaging the brake 44 (for braking action). It will be appreciated that all of the clutch and turbine mechanisms 51, 51a, 58 and 59 are fluid (i.e., hydraulic) devices since the rigidity of the interconnections established by mechanical clutches would not accommodate the quick directional reversals described.

The direction of rotation of the rotor sections of the turbines 40 and 40' and compressors 39 and 39' is essentially independent of the rotatory conditions of the main shaft 25, outer housing 21, cam track casing 30, and main rotary shell 63 because the compressors are mechanically driven by the turbines and the directions of rotation of the turbine is predetermined by the blades thereof and orientation of the nozzles discharging the exhaust gases thereagainst. However, function of the turbines and compressors is not independent of the other components of the engine apparatus because the turbines are driven by the gaseous discharge from the respectively associated piston-cylinder structures 36,34. Accordingly, as the requirement for output power delivery to the shaft 26 decreases and the piston-cylinder structures fire less frequently and/or the

pistons are displaced at a lesser extent within their cylinders, there is a correspondingly diminished delivery of gaseous energy from the piston-cylinder structures to the turbines 40 and 40' whereupon the compressed air output of the compressors 39 and 39' decreases. Nevertheless, and as will be explained in greater detail hereinafter, a bypass system is arranged with the compressors and piston-cylinder structures so that any compressed air delivered to the combustion assemblies 32 and 32' which is not used in its entirety at any particular time is recycled and thereby causes no complications.

In the case of multiple-type engine apparatus such as the dual engine apparatus 20 illustrated, the combustion assemblies 32 and 32' are united so that they are forced to operate in the same angular directions. In the apparatus shown in FIG. 1, integration is provided by a shell or housing 63 extending between and interconnecting the combustion assemblies 32 and 32' so that they are movable in mechanically enforced synchronism. The shell has openings therein enabling atmospheric air to be drawn into the compressors 39 and 39', as shown, and blades or vanes 63a may be provided along the shell to facilitate such inward air flow. The shells or "stator" components of the turbines 40 and compressors 39 are secured to the shell 63 so as to rotate therewith which obviates seal complexities as between these devices and the combustion assemblies.

DETAILED DESCRIPTION

The detailed description of the engine apparatus will consider first the combustion chamber assemblies and, in particular, the assembly 32. For this purpose FIGS. 3 through 7 will be most pertinent, and it will be understood that the description applies equally to the combustion assembly 32'.

As previously indicated, the combustion assembly 32 includes three piston-cylinder structures 36, 34, and the suffixes a, b and c are associated with the various numerals to differentiate one such structure and the components associated therewith from the others. In FIG. 3, the pistons 36a and 36b are respectively illustrated in their opposite extreme positions of minimum and maximum compression, whereas the piston associated with the cylinder 34c although not specifically illustrated will be understood to be in a position intermediate these two extremes. It may again be emphasized that there is no compelling requirement for the three piston-cylinder structures, and the apparatus 32 in certain environments may have as few as one piston-cylinder structure and as many in excess of three as is practicable with reference to the size and output horsepower requirements of the engine apparatus.

Each piston 36, as shown best in FIGS. 5 and 6, has a hollow cylindrical component having a depending skirt 65 open at its lower end and closed at its upper end with a head or transverse wall 66. Intermediate the ends of the skirt 65 a plurality of axially spaced walls 67 and 68 may be provided, and the wall 67 is a support wall welded or otherwise fixedly secured to the skirt within the interior thereof. The walls 67 and 68 are respectively provided with relatively large openings 69 and 70 adapted to pass relatively large volumes of air therethrough, as will be described more specifically hereinafter, and the wall 68 is axially displaceable

within the skirt 65. At its lower open end, the piston 36 is equipped with a connector 71 that is welded or otherwise rigidly secured to the skirt 65, and the connector has a large opening 72 therein adapted to seat a pivot pin therein which is generally in the nature of the wrist pin used in conventional pistons. Accordingly, the peripheral surface of the opening 72 may be equipped with a sleeve bearing.

The top wall or head 66 of the piston 36 is imperforate except for the provision of a plurality of air inlet openings or ports therein, there being four such ports in the piston 36 spaced apart by equal angular distances. Respectively associated with the air inlet ports are a plurality of inlet valves 74, 75, 76 and 77. Each of the inlet valves is reciprocable with respect to the inlet port associated therewith so as to seal the same or to permit free passage of air therethrough. In this respect, each of the valves is equipped with a rod 78 extending downwardly through an opening in the support plate 68 and bearing 79 associated therewith, and it further passes downwardly through the reciprocable plate 68 and threadedly receives a nut 80 bearing upwardly against the underside of the plate 68. A helical compression spring 81 coaxially circumjacent the rod 78 intermediate the plates 67 and 68 bears at its upper end against the support plate 67 and at its lower end seats upon the plate 68 through a support 82 and thereby resiliently biases the plate 68 downwardly so as to force the valve 74 against the seat therefor.

Each of the valves 74 through 77 is similarly associated with the plates 67 and 68 so as to have stems slidably reciprocable through the plate 67 and movable with the plate 68 which is ordinarily biased toward a downward position by the compression springs 81. However, all of the valves 74 through 77, which function in mechanically enforced synchronism so as to be concurrently opened and concurrently closed, are displaceable into the open positions thereof by upward movement of the plate 68 which is slidably reciprocable within the skirt 65 and has an inner end portion of a plunger or piston rod 84 pivotally connected thereto through a clevis 85. The outer end of the rod 84 is operatively connected with a crank effective to displace the rod 84 and plate 68 inwardly at cyclically repetitive intervals, as explained hereinafter, so as to open the inlet valves 74 through 77 and permit air to enter the variable-volume cylinder space 86 (FIG. 3) defined between the piston head 65 and cylinder head 87 associated therewith.

Each piston connector 71 is pivotally connected via a pivot pin 88 to one end of a link 89 which at its opposite end is pivotally connected to a crank arm 90 by a pivot pin 91. Each crank arm 90 is pinned or otherwise fixedly secured to a cam shaft 92 that is longitudinally extending and parallels the main shaft 25 in radially spaced relation therewith. Each cam shaft is journaled for rotation in the casing structure 35 of the piston assembly 32 and projects outwardly therefrom into the associated cam assembly 31 for purposes to be explained hereinafter. It will be apparent from inspection of FIG. 3 that whenever the piston 36 is reciprocated linearly within the cylinder 34, the crank arm 90 oscillates or reciprocates angularly about the axis of the shaft 92 which also reciprocates angularly with the crank arm since it is affixed thereto.

During such reciprocable displacements of the piston 36, the inlet valves 74 through 76 are cyclically displaced between the open and closed positions thereof by reciprocable displacements of the support wall or control plate 68, and the plate is reciprocated by the rod 84. It should be noted that a variety of arrangements can be used to enforce reciprocable displacements upon the plate 68 including both mechanical and hydraulic system. In the particular engine 20, the valve control rod 84 is mechanically connected to the plate 68 and is reciprocated by a combination mechanical and hydraulic system (hidden in FIG. 3) which is superior to a purely mechanical system in that it affords considerably greater flexibility in timing and relating the opening and closing displacements of the inlet valves 74 through 77 to the cyclic reciprocations of the piston 36. More specifically, the stroke length of each piston 36 within the cylinder 34 therefor can be increased and decreased selectively within a predetermined maximum range, and the rate of reciprocation of the piston is also variable. Evidently, the rate at which the inlet valves are opened and closed should be increased and decreased in respective correspondence with increases and decreases in the rate of reciprocation of the pistons; and as stroke length of the piston is changed, it may be advantageous to alter the period during which the valves are maintained in their open positions during each operating cycle so as, for example, to increase the time interval that the inlet valves are open as the stroke length of the piston is decreased, and vice versa. In the apparatus being considered, ordinary cam shaft mechanism provides the time relationship of the movement of the valve lifter rod 84 with the movement of the piston 36, and the duration of the valve opening is adjustably determined by varying the effective length of the rod 84 by means of the structure shown in FIG. 5A.

Referring thereto, the rod 84 is seen to be slidably received within an extension 84' sealingly circumjacent the same, and which extension defines a pressurizable chamber 93 adapted to have a hydraulic fluid forced thereinto to displace the extension 84' downwardly relative to the rod 84 and thereby lengthen the same, or to have fluid removed therefrom to permit the extension to move upwardly relative to the rod and thereby shorten the same. A suitable control system is provided for this purpose, as will be described hereinafter, and in the shortened condition of the rod, a center pin 93' supported within the chamber 93 by spider structure enters an elongated recess 93'' in the rod to positively establish the minimum length of the composite rod and extension component.

Each cylinder 34 is equipped with a plurality of exhaust valves, there being four in the particular engine being considered, only two of which are illustrated in FIG. 3 and they are respectively denoted with the numerals 94 and 95. The exhaust valves are disposed in respective alignment with the inlet valves 74 through 77, and they have sufficient cross sectional areas at the ports associated therewith to enable the products of combustion to be expulsed from the cylinder space 86 during each cycle of operation of the piston. The valve ports controlled by the exhaust valves 94 and 95 communicate with a manifold space 96 that at one end thereof is in open communication with a longitudinally

extending collection conduit 97 adapted to convey hot combustion gases to the turbine 40, as previously noted. The valves 94 and 95 are respectively equipped with stems that slidably and sealingly extending through the walls of the manifold 96 and through bearings supported therealong and are axially reciprocable with respect to both.

The valves are resiliently biased toward the closed positions thereof by helical coil springs 98 and 99 coaxially circumjacent the valve stems, and the springs at their inner ends seat upon the bearings supported along the casing of the manifold 96 and at their outer ends seat against the enlarged inwardly turned end 100 of an angularly reciprocable valve or rocker arm 101. Each arm 101, as shown best in FIG. 4, is pivotally supported intermediate the ends thereof on a shaft or rod 102 extending longitudinally in substantially parallel relation to the main center shaft 25. The rod 102 is supported by the casing 35 of the combustion assembly 32, and the rocker arm 101 is provided with a slightly enlarged bearing sleeve 104 that is coaxially circumjacent the rod 102 and provides the pivotal engagement of the rocker arm with the rod. A spacer 105 is mounted upon the rod 102 at the approximate center thereof and extends along one side of the bearing sleeve 104 for the purpose of separating the sleeve from adjacent components, as described hereinafter.

It will be apparent that each rocker arm 101 must be cyclically reciprocated in angular directions about the axis of the associated shaft 102 so as to displace the exhaust valves connected with the rocker arm between the open and closed positions respectively shown in FIG. 3 by the valves 94a, 95a and 94b, 95b. In this reference, the compression springs 98 and 99 tend to bias the valves 94 and 95 toward the closed positions thereof and for this purpose bear upwardly against the enlarged end 100 of the associated rocker arm. It will be apparent that each valve stem is attached to the enlarged end portion 100 of the associated rocker arm so as to enable the rocker arm to close the valves when angularly displaced in a counterclockwise direction, as viewed in FIG. 3. For this purpose, each of the exhaust valve stems may be attached to the enlarged end portion 100 by means of a nut 106 that bears inwardly upon the outer surface of the associated enlarged end portion. Thus, the exhaust valves 94 and 95 are necessarily closed when the springs 98 and 99 displace the rocker arm 101 in a clockwise direction, and the valves are similarly opened because of the attachment of the nuts 106 to the end portion 100 when the rocker arm is angularly displaced in the clockwise direction.

Angular reciprocation of each arm 101 is effected by actuator mechanism 107 operative to reciprocate the associated rocker arm about the pivot shaft 102 associated therewith. The mechanism 107 includes an outer cylindrical tube or shell 108 open at one end and closed at the opposite end 109 thereof. The shell 108 is supported for angular displacements by a pivot pin or rod 110 that is longitudinally disposed and is supported in substantially parallel relation with the main shaft 25 by the casing 35 of the combustion assembly. The pivot pin 110 extends completely through the shell 108 associated therewith, and the shell is therefore angularly displaceable in clockwise and counterclockwise directions, as viewed in FIG. 3. Slidably mounted

within the shell 108 for axial displacements along the length thereof is a stroke-regulator and actuator element 111 of cylindrical configuration in cross section, and the actuator element is dimensioned so as to be snugly received within the shell 108 while being freely slideable along the length thereof.

Each actuator element 111 is provided within the interior of the associated shell 108 with an axially elongated slot 112 that passes the associated pivot pin 110 therethrough and permits the element 111 to be axially displaceable relative both to the shell 108 and its pin 110. At its outer end which is disposed exteriorly of the shell 108, the actuator element 111 is equipped with an inwardly projecting cam follower 114 adapted to ride upon a cam 115 defined along the outer surface of a cam carrier 116 mounted upon the torsion shaft 92 and keyed or otherwise secured thereto so as to prevent relative rotation therebetween. As viewed in FIG. 3, the cam carrier 116 is angularly reciprocable about the axis of the associated torsion bar 92 between the extreme positions respectively illustrated by the cam carriers 116a and 116b, and such displacements of each cam carrier causes the cam 115 mounted thereon to reciprocate the associated actuator element 111 between the outer and inner positions thereof respectively illustrated by the elements 111a and 111b.

Such angular displacements of each actuator element 111 enforced thereof by the cooperative interengagement of the associated cam follower and cam 115 causes the rocker arm 101 to be angularly displaced about the pivot axis 102 associated therewith so as to open and close the exhaust valves 94 and 95. This result is provided because each rocker arm 101 has an end portion 117 that overlies the outer end of the actuator element and is provided with a pad 118 in engagement therewith. As shown best in FIG. 4, each rocker arm 101 is turned laterally in a longitudinal direction along the axis of the main shaft 25 so as to pass through an opening 119 in a divider wall 120, and the rocker arm is then turned at generally right angles to the main shaft 25 so as to extend along and overlie the associated actuator element 111.

It will be apparent that the extent to which each rocker arm 101 is angularly displaced about its pivot axis 102 is determined by the extent to which the cam follower 114 of the associated actuator element 111 rides upwardly along the cam 115. That is to say, since each cam 115 progressively increases in height from the inner to the outer end thereof, if the cam follower 114 is caused to be positioned at the outer end of the cam when the cam carrier 116 has been rotated to its maximum position, the rocker arm 101 will be displaced in an angular direction to a greater extent so as to provide a longer and greater valve opening than when the actuator element 111 is adjusted so that the cam follower 114 only rides part way along the cam 115 when the carrier 116 has been displaced to its maximum position, as shown by the cam follower 114a and cam 115a in FIG. 3. The relative position of each actuator element 111 and its associated shell 108 can be selectively adjusted, and the means by which this is accomplished includes in part a centrifugally actuated stop assembly 121 operatively associated with the shell 108 and actuator element 111. As shown most clearly in FIG. 7, the stop assembly 121 includes a relatively

flat bearing disc 122 rotatably mounted upon the pivot pin 110 so as to be freely rotatably with respect thereto, a sleeve bearing being included for this purpose. The disc 122 lies within a generally rectangular channel 124 formed in the actuator element 111. The channel 124 is slightly wider than the thickness of the plate 122 so that the actuator element 111 is freely movable in axial directions along the shell 108 with substantially no interference resulting from the presence of the disc.

The stop assembly 121 further includes a stop pin 125 extending through the disc 122 and projecting outwardly from each side thereof so as to be received within an elongated slot 126 formed in the actuator element 111 in substantially parallel relation with the aforementioned slot 112. The slot 112 may be slightly longer than the slot 126 so as to cause any abuttable interengagement between the actuator element 111 and stop assembly 121 to be established between the stop pin 125 and terminal ends of the slot 126. A flyweight 127 mounted upon a support arm 128 is located a spaced distance outwardly from the disc 122 to which the arm 128 is fixedly secured. The arm 128 extends through the channel 124, as illustrated in FIG. 7. An abutment element 129 also fixedly secured to the disc 122 extends outwardly therefrom through the channel 124 on the side thereof opposite that of the support arm 128. Since the pivot pin 110 and stop pin 125 are offset with respect to each other, angular displacements of the disc 122 about the axis of the pin 110 causes the stop pin 125 to be displaced through a relatively flat arc and generally along the length of the slot 126 and, as will be explained in detail, the specific location of the stop pin 125 determines the extent to which the actuator element 111 can be displaced relative to the sleeve 108 which, in turn, establishes the degree of angular displacement of the rocker arm 101 and extent to which the exhaust valves 94 and 95 are opened.

Each actuator element 111 is biased outwardly abutment with the pin 25 by a compression spring 123 operative between the actuator and end wall 109 of the associated shell 108. As shown most clearly in FIG. 3, each stop assembly 121 is resiliently biased in a counterclockwise direction such that the flyweight 127 thereof tends to be forced inwardly by a helical tension spring 130 attached at one end to the abutment element 129 of the associated stop assembly and at its opposite end to a bracket 131 fixedly secured to the end wall of the associated shell 108. The counterclockwise biasing force imparted to each stop assembly 121 and flyweight 127 thereof by the spring 130 is counteracted and overcome by centrifugal force developed by the flyweight as the combustion assembly 32 is rotatably driven during operation of the engine apparatus 20. That is to say, the spring force tending to rotate the stop assembly 121 in one direction about the axis of the pivot pin 110 is overcome by the centrifugal force developed during operation of the engine apparatus which tends to force each flyweight 127 outwardly so as to pivot the stop assembly in the opposite direction about the axis of the pivot pin.

However, the extent to which such centrifugal force is permitted to displace the stop assembly angularly is selectively determined and adjusted by means of a control in the form of a piston 132 axially reciprocable within a cylinder 134 and equipped with a rod 135

defining a stop against which the abutment element 129 is movable. The piston-cylinder structure 132,134 is a two-way fluid motor (specifically hydraulic) in which the piston can be moved positively in either direction and then held in any position of adjustment as a consequence of the fluid pressure operative on opposite sides of the piston. The extent to which the stop rod 135 projects from the cylinder 134 establishes the maximum permissible angular displacement of the stop assembly 121 as a result of centrifugal force operative thereon and, therefore, establishes the extent to which the actuator element 111 is displaceable within the shell 108 during any specific operating mode of the engine apparatus and combustion assembly 32 thereof.

The aforementioned cam carrier 116 also has a positioning cam 136 located along the outer peripheral surface thereof in angularly spaced relation with the actuator cam 115. The cam 136 is operatively arranged with a cam follower 137 somewhat in the form of a bell crank or L-shaped component pivotally supported intermediate the ends thereof on a pin 138. The outer leg or branch of the cam follower 137 extends through an opening 139 in the shell 108 and into a recess 140 formed in the actuator element 111. The two legs or branches of the bell crank cam follower 137 are angularly displaceable with respect to each other and are interconnected by a torsion spring, and the function of the cam follower in association with the cam 136 is to displace the actuator element 111 inwardly or in an inward direction relative to the shell 108 to the maximum permissible extent determined by the particular location of the piston 132 and stop rod 135 thereof at any specific adjustment of the control assembly.

In this respect, and assuming as the starting condition the relative positions of the components associated with the stop assembly 121b, when the engine apparatus is in operation and the combustion assembly 132 rotating, the flyweights 127 will swing outwardly until the abutment elements 129 are in engagement with the stop rods 135 so that the stop pins 125 will be in a somewhat forward location as concerns the terminal ends of the slots 126 so that the actuator elements 111 are free to be displaced within the shells 108 within the limits defined by the stop pins and slots. The piston 36b is in substantially the innermost position thereof defining maximum compression within the variable-volume space 86, so that all of the valves including the exhaust valves 94b and 95b are closed. Therefore, the cam follower 114b is remote from the actuator cam 115b, and the positioning cam 136 is remote from the bell-shaped cam follower 137b.

As the torsion bar 92b and cam carrier 116b mounted thereon are displaced angularly in a clockwise direction toward the positions of the torsion bar 92a and cam carrier 116a, the positioning cam 136b will move toward the cam follower 137b and eventually engage the same so as to rotate such cam follower in a counterclockwise direction about its pivot pin 138 whereupon the cam follower will engage the terminal end of the recess 140 so as to displace the actuator element 111b inwardly within the shell 108b until inward movement is terminated by abutment of the stop pin 125b with the end of the slot 126b. If such abutment should occur before the angular displacement of the cam carrier 116b terminates, the force applied by the

cam 136 to the cam follower causes the two legs thereof to move relative to each other, as shown by the cam follower 137a. At about the same time that the positioning cam 136 engages the cam follower 137 associated therewith, the actuator cam 115 is moving into engagement with the cam follower 114 associated therewith so as to commence actuation of the associated rocker arm 101 so as to open the exhaust valves 94 and 95. As previously explained, the extent to which such valves are opened depends upon the limiting position assumed by the actuator element 111 as enforced thereon by the contemporary adjustment of the associated piston 132 and stop rod 135 thereof because such limiting position of the actuator element determines the extent to which the cam follower 114 rides onto the cam 115.

Contrariwise, when the piston is in the most retracted position thereof representing maximum volume of the space 86, as depicted by the piston 36a and space 86a, movement of the cam carrier 116 and torsion bar 92 upon which it is mounted in the opposite direction (counterclockwise referenced to the torsion bar 92a in FIG. 3) the cam 115a will be displaced with respect to the cam follower 114a toward the position shown by the cam follower 114b and cam 115b in which disengagement is effected and the exhaust valves are returned to their closed positions by operation of the compression springs 98 and 99. At the same time, the positioning cam 136b is displaced from the cam follower 137a so as to release the positioning force otherwise applied thereby to the associated actuator element 111. It will be appreciated that both the extent to which the exhaust valves 94 and 94 are opened by the rocker arm 101 and the period or length of time during which such valves are held open during any one cycle of operation are functions of the position of the actuator element 111. More particularly, if the cam follower 114 is caused to ride onto the associated cam 115 to a greater angular extent, the associated rocker arm 101 will be displaced angularly through a greater distance about its pivot pin 102 and, therefore, for any particular angular velocity or periodicity of the torsion bar 92 and cam carrier 116, a greater time period will be required for completely engaging the cam and cam follower to the maximum permissible extent and for thereafter disengaging such two components.

Each of the piston-cylinder structures 36,34 is equipped with a fuel delivery system by means of which fuel for combustion is supplied to the variable-volume cylinder spaces 86. In the engine apparatus 20 and combustion assembly 32 thereof, such system is a fuel injection system comprising a plurality of fuel nozzles 141 projecting into the respective cylinder spaces 86 such as through the closure wall 87 of each cylinder 34. As respects the present invention, the fuel injection system may be conventional and, for example, may comprise a system in which fuel under pressure is delivered to the respective nozzles 141 via a plurality of fuel control valves 142 that are normally closed and are opened in a cyclically repetitive manner to enable predetermined quantities of fuel to be injected into the cylinder spaces through the nozzles 141.

The mechanism provided for manipulating each valve 142 is substantially identical to the mechanism used to open and close the exhaust valves 94 and 95, as

previously explained. In this respect, and referring in particular to FIGS. 3 and 4, the valve-actuating mechanism includes a rocker arm 144 having intermediate the ends thereof a bearing sleeve 145 pivotally mounted upon the aforementioned pivot shaft 102 along the spacer 105 on the side thereof opposite the bearing sleeve 104 of the rocker arm 101. Adjacent one end, the rocker arm 144 has an end portion 146 connected to a reciprocable plunger 147 operative to manipulate the associated valve 142 between the open and closed positions thereof. A helical compression spring 148 seats at one end upon a fixed casing of the valve 142, and at its opposite end against the end portion 146 of the rocker arm 144 via an enlargement provided for this purpose. Accordingly, the spring 148 biases the associated valve plunger 147 toward the closed position thereof, and therefore biases the rocker arm 144 in a counterclockwise direction, as viewed in FIG. 3.

The rocker arm 144 is cyclically displaced in a clockwise direction against the biasing force of the spring 148 to open the valve 142 by means of actuator mechanism 149 which is substantially identical to the aforementioned actuator mechanism 107 associated with the rocker arm 101 to manipulate the same. In this respect, the actuator mechanism 149 has a stroke regulator and actuator element 150 underlying the end portion 151 of the rocker arm 144 which extends through an opening 152 in the partition 120. The control mechanism 149 also has a shell 154 within which the actuator element 150 is reciprocable, and a centrifugally actuated stop assembly 155 regulates the position of the element 150 in accordance with the adjustments enforced thereon by a fluid actuated piston-cylinder control 156. The actuating mechanism 149 is otherwise structurally and functionally identical to the aforementioned control mechanism 107 and, therefore, need not be further described since it will be understood that the control mechanism is cooperatively associated with a cam-equipped carrier 157 mounted upon the torsion bar 92 so as to be angularly displaced thereby.

Since the engine apparatus 20 is a "gasoline-type" engine (i.e., not diesel), the combustible admixture of fuel and air compressed by the piston 36 within the cylinder space 86 is necessarily ignited by a conventional sparking device such as a spark plug 158 that projects into the cylinder space through the top closure wall 87 thereof. The spark plug 158 is connected by conductors, not shown, to an ignition system that may be completely conventional and, for this reason, is not shown. As is well known, the spark plug 158 is energized at about the time that the fuel and air charge within the cylinder space 86 is compressed to its maximum extent so as to ignite the same and thereby power the engine apparatus.

As previously noted, air for combustion and for purging the cylinder space 86 is supplied through the inlet valves 74 through 77 which are located within the cylinder 36, and the air supplied through the inlet valves is delivered thereto under pressure derived from a pump mechanism arranged with the associated piston 36 and therefore operated in timed relation with the reciprocable displacements thereof. More particularly, the aforementioned crank arm 90 has a configurated pump surface 159 disposed in facing juxtaposition with

a correspondingly configured pump surface 160 defined by a combination valve and pump element 161 mounted upon the associated torsion bar 92 so as to be angularly displaceable with respect thereto between the position extremes respectively shown by the elements 161a and 161b.

As shown in FIG. 3, the surfaces 159 and 160 define a variable-volume pumping space or chamber 162 therebetween which increases in size or cross sectional area from a very small volume (essentially zero) adjacent the torsion bar 92 toward a substantially larger outlet or discharge port 164 through which air is expressed into a cooling chamber 165. Each valve element 161 is resiliently biased toward the crank arm 90 associated therewith by a plurality of helical compression springs 166 that seat at one end against the element 161 and at their opposite ends against a fixed support 167 secured to the casing 35 of the combustion assembly. The biasing force of such springs 166 ordinarily maintains each element 161 in a position in which it closes the associated port 161, as shown by the elements 161a and 161b, but upon power-stroke displacement of the crank arm 90 toward the element 161, the pressure developed between the closing surfaces 159 and 162 causes the element 161 to be displaced against the spring face to open the port 164 and enable compressed air to be expressed therethrough, as shown by the element 161c.

Each variable-volume pumping chamber 162 cyclically changes in volume between the generally maximum and minimum capacities respectively shown by the chamber 162b and 162a as the crank arm 90 is angularly reciprocated by the piston 36 connected therewith which linearly reciprocates within the cylinder 34 associated therewith. As each crank arm 90 traverses the arcuate path between the two extremes respectively shown by the crank arms 90a and 90b, air is expelled or expulsed under pressure from the chamber 162 and port 164 thereof into the associated cooling chamber 165 and air is drawn into the chamber 162 both because of the pressure reduction in the enlarging pumping chamber 162 as the surface 159 recedes from the surface 160 and because of the superatmospheric pressure imparted to atmospheric air drawn into the engine apparatus as it passes through the aforementioned turbine-driven compressors 39.

As respects the pressure-reducing tendency, each crank arm 90 has an end portion 168 provided with an arcuate outer edge that closely approaches a correspondingly-curved wall 169 extending longitudinally between the spaced walls of the casing 35 and forming one of the boundaries of the pumping chamber 162. Accordingly, very little leakage is afforded between the facing arcuate surfaces of the crank arm end portion 168 and boundary wall 169 so that as the pumping surface 159 recedes from the surface 160, a reduced pressure tends to be developed within the progressively-increasing volume of the pumping chamber 162. As respects pressurization of air delivered to the chamber 162, the function of each compressor 39 is to supercharge or precompress the air delivered to the combustion assemblies 35. Accordingly, each compressor 39 tends to force air into the chambers 162 connected therewith, especially as the capacity or volume thereof increases. Simple check valves may be interposed

between each chamber 162 and the compressor 39 associated therewith so as to permit the free flow of air from the compressor into each chamber but to prevent flow in the reverse direction as the pressure in each chamber 162 is increased by movement of the crank arm 90 thereof toward the associated element 161.

Each cooling chamber 165 is provided with an outlet port communicating through a flow conduit 170 with the open lower end portion of the associated cylinder 34 and, more particularly, with a chamber 171 in open communication with the lower end portion of the associated cylinder. Accordingly, as the pumping surfaces 159 and 160 approach each other because of the angular displacement of the crank arm 90 toward the pumping element 161, the compressed air expelled from the pumping chamber 162 into the cooling chamber 165 is forced through the flow conduit 170 and into the chamber 171 and, therefrom, through the open inlet valves 74 through 77 into the combustion chamber 86 and outwardly therefrom through the exhaust valve 94 and 95 into the exhaust manifold 96. The relatively large-volume flow of pressurized atmospheric air through the combustion chamber 86 purges the chamber of exhaust gases from a prior cycle of combustion occurring therein and it also supplies the air necessary for the subsequent cycle of combustion, and which supply of air is at a superatmospheric pressure thereby increasing the efficiency of combustion. Check valves 173 adjacent the chambers 171 prevent reverse flow of air through the conduits 170.

The quite massive volumetric flow of air through the combustion chamber 86 also cools the chamber and, in more particular terms, cools both the piston 36 and cylinder 34 as well as the exhaust valves 94 and 95 and other components operatively associated with the piston-cylinder structure. In this reference, the cooling chambers 165 have a plurality of flow conduits 172 extending therethrough which form a part of the liquid (usually water) cooling system of the engine apparatus, and the air moving through each cooling chamber comes into heat-exchange relation with the cooling conduits 172 so as to have the temperature thereof reduced. Thus, the air-cooling function defined by the chamber 165 and conduits 172 therein tends to extract heat added to the atmospheric air both in the turbine compressors 39 and in the pumping chamber 162 as a consequence of the generally (although certainly far from perfect) adiabatic compression of the air occurring at the compressor and pumping stations.

Further, since substantial turbulence occurs within each cooling chamber 165 because of the function of the pump or positive-displacement compressors defined by the crank arms 90 and each pumping element 161 associated therewith, the efficiency of the heat exchange or heat extraction from the air is significantly maximized, thereby extracting from the air a greater quantum of heat than that added thereto by the compression cycles. Therefore, the compressed air pumped through each piston 36 and combustion chamber 86 has a much greater cooling capacity than would otherwise be the case.

The relatively large openings 69 and 70 in the intermediate piston walls 67 and 68 affords very little inhibition to the free flow of air therethrough, and correspondingly the plurality of inlet valves 74 through 77

in the piston head 69 provides in the aggregate a large cross sectional area through which the air can flow with minimal restriction. The same is true of the relatively large area defined in the aggregate by the exhaust valves 94 and 95 in the cylinder head 87. Consequently, the cooling function afforded by the temperature-reduced air contributes significantly to the efficiency and cool running of the engine apparatus. Nevertheless, each cylinder 34 may be equipped with the usual liquid-cooling jacket 174.

It may be noted that each receiving chamber 171 is equipped with a bypass flow system by means of which air is returned to the associated cooling chamber 165 in the event that there is no requirement for the excess within the combustion chamber 86. The bypass system includes a return flow conduit 175 in open communication at one end with the associated cooling chamber 165, and in open communication at its opposite end with a relatively small expansion chamber 176. The chamber 176 communicates with the receiver chamber 171 through a relatively large inlet port 177 which is closed by the piston 36 when in its lowermost position, in the particular engine apparatus 20 being considered, as depicted by the piston 36a in FIG. 3. With this general arrangement, any compressed air pumped into the receiver chamber 171 from the pumping chamber 162 via the flow conduit 170 is simply returned to the cooling chamber 165 if there is no other escape therefor from the receiver chamber 171 through the inlet port 177, expansion chamber 176, and returned conduit 175. Check valves 183 are provided in the conduits 175 to prevent reverse flow of air, and pressure relief valves may be included in association with each chamber 171 to limit the maximum permissible pressure attainable therein. The bypass arrangement is useful in certain operating modes of the engine apparatus, as will be described hereinafter.

For convenience of manufacture and especially for convenience of maintenance, the combustion assembly 32 may be comprised of a plurality of individual modules that can be moved and replaced as integers without significant interference with or need to replace other modules. Generally stated, each module in the particular engine apparatus being described includes a piston-cylinder structure and essentially all of the components operatively associated therewith and mechanically connected or otherwise coupled thereto. Thus, in FIG. 3 such modules are illustrated and are respectively bounded by the arcuate tubular sleeve segments 178a, 178b, and 178c and all of the divider-support walls and frame components directly or indirectly connected therewith including the aforementioned divider walls 120a, 120b, and 120c. The latter divider walls 120 may be releasably secured to the casing 35 of the combustion assembly 32 by threaded cap screws or other conventional means (not shown) and the sleeve segments 178 are coaxially circumjacent the main shaft 25 and are slidable therealong when released therefrom and when the divider walls 120 respectively associated therewith are released from the casing 35 so as to permit an entire module to be withdrawn axially from the interior of the combustion assembly for repair and/or replacement. It will be recalled that the combustion assembly 32 has been considered to be constrained upon the shaft 25 so as to rotate therewith, and any

conventional arrangements (keys or splines, for example) may be provided to effect such rotational constraint while permitting the modules and shaft to be displaced longitudinally with respect to each other. However, the rotational constraint of import is between the combustion assembly and main rotary whether the latter be the shaft 25 and/or the shell 63, as previously noted.

Briefly describing a cycle of operation of the combustion assembly 32, and assuming as the starting condition the disposition of components illustrated in FIG. 3, the piston 36b is at the end of its compression stroke so that ignition of the compressed combustible charge within the combustion chamber 86b will displace the piston through its power stroke, thereby angularly displacing the crank arm 90b through an arcuate distance of the general order of 45° toward the pump element 161b. As a result, the associated torsion bar 92b is angularly displaced through the same arcuate distance, and such displacement thereof is used in developing the power output of the engine apparatus. After the piston 36b has been displaced through a linear distance generally approximating about one-half the length of the cylinder 34b, the inlet valves 74b through 77b and exhaust valves 94b and 95b are opened, respectively, by the hydraulic system associated with the inlet valves via the reciprocable plate 68b and rod 84b arranged with the piston 36b and by the rocker arm 101b and actuator mechanism 107b. As a result, continued displacement of the crank arm 90b toward the pump element 161b causes the diminishing volume of the pump chamber 162b to express compressed air into the combustion chamber 86b via the cooling chamber 165b, flow conduit 170b, receiver chamber 171b, and inlet valves associated with the piston 36b. Such flow of compressed air into the combustion chamber 86b leaves the same via the open exhaust valves (the assemblage now having the condition depicted by the piston-cylinder structure 36a, 34a), thereby purging the combustion chamber of the exhaust gases remaining after combustion.

Shifting now to the condition depicted by the piston-cylinder structure 36a, 34a and components associated therewith since the piston-cylinder structure 36b, 34b will be in such condition following the half cycle described, as the piston 36 begins to move inwardly toward the cylinder head 87a, the inlet valves 74a through 77a and exhaust valves 94a and 95a are closed, whereupon further linear displacement of the piston within the cylinder will compress the air charge then confined within the combustion chamber between the cylinder head 87a and piston head 66a moving theretoward. Thereafter, a charge of fuel is ejected into the combustion chamber through the nozzle 141a as a consequence of the rocker arm 144a being displaced by the actuator mechanism 149 associated therewith, as previously described. At approximately the top of the compression stroke of the piston 36a, the ignition system causes the plug 158a to ignite the compressed combustible charge, whereupon the power stroke of the piston 36a commences. Accordingly, a complete cycle of operation of the two-cycle gasoline-type engine apparatus specifically being considered has been described.

The multiplicity of piston-cylinder structures 36,34 comprised by the combustion assembly 32 serves substantially the same function as multiple piston-cylinder arrangements in any conventional engine: namely, providing smoother operation by delivering a succession of closely spaced power impulses, each of which may be of relatively small magnitude, in contrast to the delivery of larger-magnitude power pulses at more widely spaced intervals. Thus, the piston-cylinder structures 36a, 34a and 36b, 34b may have an out-of-phase relationship (i.e., 180° out-of-phase), and the piston-cylinder structure 36c, 34c may have an intermediate phase relationship with respect thereto. In each instance, however, the respective torsion bars 92 are positively displaced angularly in succession, and such angular displacements thereof are used in the cam assembly 31 to provide output power at the shaft 26 in the manner now to be described.

In this respect a detailed description of one of the cam assemblies 31 will now be set forth, and reference will be made in particular to FIGS. 8 through 12.

First returning briefly to FIG. 1, the linkage 37 illustrated diagrammatically in this figure which transmits power developed by the reciprocable pistons 36 of the combustion assembly 32 to the cam assembly 31 includes the aforementioned torsion bars 92, and they extend longitudinally from the combustion assembly into the cam assembly in generally parallel relation with the main shaft 25. Also, the cam track 38 in operative association with the linkage 37 includes, as shown best in FIG. 9, a pair of longitudinally spaced cam plates 179 and 180. As illustrated in FIG. 2, each of these plates is fixedly secured along the peripheral edge thereof to the cam truck casing 30 so as to prevent relative rotation therebetween. Any suitable means may be used to effect such fixed mechanical interconnection between the cam plates and casing, such as bolts and threaded apertures therefor neither of which are shown. The main shaft 25, it will be recalled, is freely rotatable with respect to the cam assembly 31, and such freedom is structurally depicted in FIGS. 8 and 9 by the spatial separation therebetween.

The torsion bars 92 are respectively equipped at the terminal end portions thereof within the interior of the cam plates 179 and 180 with links or cams follower arms 181 each of which is equipped at the inner end thereof with a rotatable cam follower 182 generally in the form of a cylindrical roller bearing assembly mounted upon a stub shaft 184 carried by the arm 181.

The cam plates 179 and 180 are substantially identical, and they have open interiors configurated to define a continuous cam track or surface generally denoted with the numeral 185. Each of the cam followers 182 is adapted to rigidly engage the cam track 185 which, in the particular form shown, has a somewhat cloverleaf configuration defined by four equally spaced recess-type lobes alternating with four equally spaced risers respectively separating the successive lobes. For convenience of subsequent description, the four lobes are respectively denoted with the numerals 186a through 186d, and the risers are respectively denoted with the numerals 187a through 187d. Since the torsion bars 92 are angularly displaced in alternate opposite directions about the axes thereof, as previously explained, the cam followers 182 are necessarily displaced through a

corresponding angular distance describing a segment of a rotary arc about the axis of the associated torsion bar or, as viewed in FIG. 8, alternatively in clockwise and counterclockwise directions.

The cam followers 182 are actually driver components that impart rotation to the cam plates 179 and 180 relative to the torsion bars 92 and combustion assembly 32 about the longitudinal axis of the main shaft 25 (depending upon the particular engine apparatus being considered, and any contemporaneous operating mode thereof, the cam plates 179 and 180 may be stationary and the combustion assembly 32 rotated, the combustion assembly may be stationary and the cam plates 179 and 180 rotated, or both may be rotating in the same or in opposite directions). Such relative rotation is effected by the torque developed between the cam 185 and surfaces of the various cam followers 182 upon the power strokes of the pistons 36 respectively associated therewith.

More particularly in this reference, as each cam follower 182 travels outwardly along the inclined surface of the cam 185 interconnecting the highest or innermost point of any riser 187 and the lowest or outermost point of the next successive lobe 186, at any instant an essentially tangential contact is defined between such inclined surface and the cam follower ridingly engaging the same. The force developed between the cam surface and follower at such tangential point of contact will be radially oriented relative to the center of the cam follower and will be outwardly directed toward the circumferential surfaces of the cam plates 179 and 180 via the cam-configurated surface 185 thereof. Such force is divisible into its vector components one of which is oriented so as to develop a torque or angularly-oriented force component operative between the cam and follower tending to enforce relative rotation thereon about the longitudinal axis of the main shaft 25. Such rotation-enforcing torque is of progressively changing magnitude being of greatest magnitude adjacent the various risers 187 and of diminishing magnitude toward a minimum adjacent the outermost extremities of the cam lobes 186. However, because of the phasic relationship of the various pistons 36, as heretofore explained, the torque development progresses from cam follower to cam follower, thereby resulting in a relatively uniform rotation-enforcing torque development between the cam plates 179, 180 and the cam followers 182 and combustion assembly 32 arranged therewith.

Further to this point and referring to FIG. 11, the cam 185 in illustrative configuration is plotted along a position or time scale denoted "cycle time" subdivided below the axis line into angular cam-intervals of 45° and above the line into angular follower-intervals of 120°. Since the cam 185 has four risers 187 and four lobes 186 respectively alternating therewith, the risers are spaced apart by 90° intervals as are the lobes, and the center-to-center distance between each riser and the lobes bordering the same is approximately 45°. The particular engine apparatus 20 has three cam followers 182 in each cam assembly 31, and the cam followers are angularly separated by 120° intervals, as shown in FIG. 11. This figure also depicts the relative condition of the cam followers 182 and cam 185 illustrated in FIG. 8, wherefore the follower 182a is about at the

midpoint of the riser 187d and is about to move outwardly through its power stroke, the follower 182b has completed its power stroke and is about to commence its return stroke since it is approximately 180° out of phase with the follower 182a, and the follower 182c is being displaced outwardly through its return stroke and is riding inwardly along the inclined surface of the cam 185 interconnecting the riser 187c and lobe 186c. The directions of movement of each of the followers 182a is indicated in FIG. 11 by the arrow-equipped lines respectively extending through the centers of the followers 182. As heretofore explained, all of the followers 182 are being displaced angularly relative to the cam 185, and in FIG. 11 the previously adapted connection is followed in which the followers are taken to be moving from left to right (clockwise in an angular sense) relative to the cam 185. The two directions of relative movement of the cam and followers are shown by arrows in FIG. 11.

In terms of the cycle illustrated, the cam follower 182c is being displaced inwardly (i.e., downwardly) by the cam along an arcuate path about the center of the torsion bar 92c (depicted by a small origin circle in FIG. 11), and as a consequence the cam 185 is necessarily being displaced toward the left relative to the followers or, conversely, the followers are being displaced toward the right relative to the cam. The cam follower 182b has just completed its power stroke and is about to commence its return movement through the arcuate path depicted about the center defined by the torsion bar 92b. The cam follower 182a is about to initiate its power stroke and will be positively displaced through the arecuate path defined about the center torsion bar 92a so as to drivingly engage the inclined cam surface defined between the riser 187d and lobe 186d. Accordingly, the aforementioned phasic relationship is seen to exist in which the cam followers 182a and 182b are approximately 180° out of phase as respects their functional relationship (i.e., the follower 182a is initiating its return stroke, and vice versa), and the cam follower 182c is in substantial phase quadrature with the followers 182a and 182b and is at about the midpoint between the two extremes of the riser 187c and lobe 186c.

It will be apparent that the magnitude of the force imparted to the cam plates 179 and 180 by each follower 182 is magnified (disregarding the subdivision of the force into its vector components) over the torque imparted by the associated torsion bar 92 by the length of the lever arm defined between the torsion bar and follower. Also, the force imparted by each follower will appear along the entire inclined surface defined between any riser and the next successive lobe although the magnitude of the force effecting relative rotation between the cam followers and cam plates will vary all along the length of the cam surface. It may be observed, however, that in the particular engine apparatus 20 under consideration, the magnitude of the angular force developed between the cam followers and cam is relatively uniform, as is most evident in FIG. 11.

More especially in this respect, the magnitude of the force applied by any follower will progressively diminish from a maximum value adjacent any riser 187 to a minimum value adjacent the lobe 186. The phase

quadrature relationship defined by the three followers 182 produces an aggregate force that results from the sum of the force components imparted by at least two of the followers being active against the cam for the greater part of each cycle. In FIG. 11, the follower 182c is seen to be at about the midpoint of its path of travel between the riser 187c and lobe 186c, and at this instant the followers 182b has completed its force application against the surface extending between the riser 187a and lobe 186b although just prior to this instant it was applying a force to the cam, thereby contributing with the other followers to the aggregate or total force being applied thereby to the cam. At this same instant, the follower 182a is about to impart a positive driving force to the cam 185, and will them be contributing to the total magnitude of the driving force developed by the followers against the cam.

The angular displacement of each cam follower 182 and, therefore, the linear displacement of the piston 36 associated therewith can be decreased to less than full-stroke-displacement by reducing the depth of each lobe 186 or total length of the cam surfaces defined between each riser 187 and lobe 186. In FIG. 8 the length of each cam surface is at maximum, and each follower 182 cycles angularly in clockwise and counter-clockwise directions between the innermost and outermost positions respectively illustrated by the followers 182a and 182b. These maximum inner and outer positions respectively correspond to the maximum up-stroke and downstroke positions of the respectively associated pistons 36; and in this connection, it should be noted that the relative position of the followers 182a and 182b, as shown in FIG. 8, is 180° out of phase with the pistons 36a and 36b in the positions thereof illustrated in FIG. 3 (that is to say, the engine has progressed through an additional one-half cycle as between the positions of the components respectively illustrated in FIGS. 8 and 3).

Referring to FIG. 12, it will be seen that the length of each cam segment has been reduced by placing intermediate each riser 187 and the next successive riser an alternate lobe-forming component 188. Each component 188 is in the nature of a finger having a somewhat arcuate configuration, and it is supported upon a pivot pin 189 for angular displacements between the outer positions shown in FIG. 8 in which they are inoperative or ineffective to influence the configuration of the cam 185 and the inner positions shown in FIG. 12 in which they significantly reduce the depth of each cam lobe. The components 188 are selectively adjustable throughout the entire range defined between their outermost inoperative positions shown in FIG. 8 and their maximum inner positions in which they minimize the cam lobe depths by establishing a mechanical abutment projecting thereacross.

Adjustment can be effected by a variety of control arrangements, and in the engine 20 such arrangement takes the form of a fluid motor means comprising hydraulic piston-cylinder structure associated with each pivot pin 189 so as to displace the same and, therefore, the component 188 fastened thereto. More especially, each pin 189 is longitudinally disposed and extends through and is rotatable with respect to the cam plate 179 and 180, as shown in FIG. 9. For purposes of stabilization, each pin 189 may be journalled

within a bearing 190 clamped or otherwise affixed to the plate 180. Spaced from the plate 180, each pin 189 is equipped with a link 191 that is constrained against rotation with respect thereto. Pivotally secured to the link 191 is a rod 192 of a piston forming a part of the aforementioned fluid motor means which further comprises a cylinder 194 within which the piston (not shown) is reciprocable and is connected with the rod 192. The cylinder 194 adjacent the end thereof opposite the rod 192 is pivotally secured to the cam plate 180 by means of a fastener 195. Each piston-cylinder structure 192,194 is double-acting so that the precise position thereof can be positively determined and maintained, thereby permitting a corresponding degree of adjustment and maintenance of the position of each cam component 188.

It will be understood that each cam lobe 186 is equipped with a cam component 188 and that each cam component has a fluid motor means operatively arranged therewith. Accordingly, there are four separate components 188 and motor means therefor, as seen best in FIG. 2, and they are differentiated with the suffixes a through d. The various motor means are susceptible of individual adjustment so that the cam components 188 could have different positions of adjustment, but in the usual instance such components will be concurrently adjusted to the same positions so that the engine apparatus will have a condition of symmetry as respects its operating cycle. Also, each motor means will have a fluid by-pass system arranged therewith so that it can be overpowered by the pistons 36 to displace the cam components 188 outwardly in the event that the fuel charge to each combustion chamber is not properly tailored to the accommodation required by any position of adjustment of the cam components 188.

It will be clear that as between the positions of adjustment of the components 188 as shown in FIGS. 8 and 12, respectively, the magnitude of the total force imparted by any follower 82 to the cam 185 will be substantially greater when the components 188 are in their outer positions because each follower will be active against an inclined segment of the cam surface for a much longer time period and through a much greater angular distance. Thus, a maximum power condition is shown in FIG. 8 and a greatly reduced power setting is illustrated in FIG. 12. As previously explained, as well as the followers 182 being operative against the cam 185 for a shorter period and distance, the reciprocable travel of each piston 36 will be greatly reduced when the cam assembly 31 has the configuration shown in FIG. 12. In FIG. 11, the reduction in effective cam length is indicated by broken lines bearing the same reference numeral as the components 188.

The adjustable cam components 188 are configurated so as to blend into the inner surface of the cam 185 at any position of adjustment, and also accommodate relative rotation of the cam plates 179, 180 and cam followers 182 in opposite directions, thereby enabling the engine apparatus to have any of the various operating modes heretofore explained. As illustrated in FIGS. 8 and 12, the cam plates 179 and 180 may be taken to be rotating in a counterclockwise direction relative to the followers 182 or, for purposes of simplification, may be considered to be stationary in

a rotational sense with the followers rotating in a clockwise direction relative thereto. The followers also cycle angularly about the axes of their respective bars 92 between the inner and outer positions shown by the followers 182a and 182b, respectively. Similarly, in FIG. 11, the cams 179 and 180 may be taken to have a fixed position along the cycle-time scale with the followers 182 moving from left to right along such scale and relative to the cams.

The primary function of the cam components 188 and adjustability thereof is to enable the stroke length of each piston 36 to be tailored to the power requirements of the engine apparatus in accordance with changes in the load thereon such as those load changes occasioned by variations in the operating velocity of the engine and accelerations and decelerations associated therewith. For example, as the velocity of any vehicle equipped with the engine apparatus 20 is increased to a relatively constant value so that there is essentially no acceleration or deceleration, the requirement for delivery of power to the vehicle correspondingly decreases. The engine apparatus can then be made to deliver less power which can be accomplished by altering the configuration of the cam 185 by moving the cam components 188 inwardly, thereby decreasing the stroke length of each piston 36. As previously explained, such adjustment of stroke length can be made independently of or in combination with a change in the firing rate of the piston-cylinder structures 36,34 so that in any case, only that degree of power is delivered by the engine apparatus which is required to accommodate the contemporary value of the load on the output shaft 26.

As previously explained, the turbines 40 may be completely conventional and they are energized by exhaust gases delivered thereto through the respectively associated combustion assemblies 32 and, in particular, through the collection conduits 97 shown structurally in FIG. 3 and somewhat diagrammatically in FIGS. 17 and 18, to which reference will be made in particular in describing briefly the flow path of the exhaust gases through each turbine and the engine comprising the same.

Each turbine 40 may be a radial-type turbine in which the exhaust gases from the collection conduits 97 are ejected against the blades of the turbine through nozzle structures of conventional design which are located at the points of mergence of the collection conduits 97 with the turbine and denoted generally with the numeral 196. In the three cylinder engine apparatus under consideration, there are three collection conduits 97 and nozzles associated therewith spaced apart by angular distances of approximately 120°. The hot exhaust gases are expressed into the turbines 40 and rotatably drive the same so as to develop sufficient mechanical energy to drive the compressors 39, as heretofore explained. The spent exhaust gases exit from the turbine 40 adjacent the periphery thereof and are carried through a plurality of angularly spaced exhaust conduits 197 into an exhaust collection chamber 198 from which they are delivered through a plurality of conduits 199 to a cooling chamber 200 in flow communication with an exhaust pipe 201 exiting to atmosphere. Accordingly, the exhaust gases from the combustion assembly 32 after having energy removed

therefrom within the turbine 40 are collected and cooled and are then discharged to atmosphere.

Similarly, exhaust gases from the combustion assembly 32' are delivered to the turbine 40' via a plurality of conduits 97' so as to energize the turbine 40' and thereby impart rotational motion to the compressor 39'. The spent exhaust gases from the turbine 40' are directed to the collection space 198 via the aforementioned conduits 197 and a plurality of conduits 202 interconnecting the turbines 40' and 40 adjacent the outer extremities thereof. Therefore, all of the exhaust gases developed within the engine apparatus 20 are channeled to the collection space 198 and are thereafter cooled within the chamber 200 before being discharged to atmosphere via the tailpipe 201.

The cooling of the exhaust gases prior to discharging the same is believed to reduce contamination otherwise introduced into the atmosphere by the exhaust gases, and especially the particulate matter and certain of the condensable gases because of their condensation and collection along the surfaces of the cooling chamber 200 and tailpipe 201, the latter also being cooled in the manner hereinafter explained. As a result, the engine apparatus 20 has a lower exhaust emission irrespective of the improved efficiency thereof considered elsewhere herein.

The turbines 40 and 40' power the compressors 39 and 39' which respectively supercharge or deliver atmospheric air in a pressurized state for combustion to the combustion assemblies 32 and 32'. The compressors will now be described, and in this connection reference will be made in particular to FIGS. 13 through 15.

In FIG. 13 the compressors 39,39' are shown in side-by-side juxtaposition with the rotors thereof affixed to sleeve structure 41 shown as coaxially circumjacent the shaft 25 and rotatably supported with respect thereto by a bearing 203. Each compressor 39, as heretofore explained with reference to the diagrammatic illustration of FIG. 1 and as shown most clearly in FIG. 18, functions to draw in atmospheric air through a plurality of openings 204, 205 and 206 respectively provided in the shell 63, housing 21 and casing 30 (see FIG. 2) and through openings 207 in the compressor shell or "stator" element. The air is elevated in pressure within the compressor 39 and is directed therefrom through a plurality of angularly spaced delivery conduits 209 to the associated combustion assembly 32 and, more particularly, into the respectively associated pumping spaces or chambers 162 thereof (FIG. 3). After utilization in the combustion assembly 32, the combustion gases are directed into the turbine 40 to drive the same prior to being discharged to atmosphere, all as previously explained. In a completely analogous manner, the compressed gases discharged from the compressor 39' are directed into the combustion assembly 32', and the combustion gases therefrom are used to drive the turbine 40' prior to being discharged to atmosphere.

As shown in both FIGS. 13 and 18, the gaseous flow through each compressor 39 is radially inwardly from the outer shell 208 thereof through the openings 207 therein toward the center of the compressor generally established by the main shaft 25 passing therethrough. Adjacent its center, the direction of air movement is reversed so that the air is caused to effect a generally

180° change in its flow path, thereby causing the air to flow radially outwardly toward the shell 28 and into an annular collection chamber or space 210 with which the aforementioned delivery conduits 209 (which are longitudinally disposed) communicate at angularly spaced locations. Such reversal in flow direction is believed to be advantageous in terms of energy development and utilization which appears at least in part as energy of compression within the compressed gaseous discharge from the compressor although it may also advantageously influence the rotational motion of the compressor. In any case, the inward and outward directions of air as it moves through each compressor 39 is effected by a blade system therewithin, as will be subsequently described.

Referring to FIGS. 13 and 15 which illustrate the intake system of the compressors 39, it will be observed that the intake openings 207 are angularly spaced along the peripheral surface of the shell 208 (see also FIG. 2) and that each such opening is arranged with a pair of angularly spaced stator blades or partitions 211 that extend radially inwardly from the shell 208 toward the center of the compressor. The blades 211, as shown best in FIG. 15, are angularly disposed and, correspondingly, the inlet openings 207 are disposed and configurated so as to conform therewith. Accordingly, alternate successive pairs of stator blades 211 define inlet passages 212 therebetween communicating with the respectively associated inlet openings 207 and projecting radially inwardly therefrom toward the center of the compressor.

The stator blades 211 are secured along the outer extremities thereof to the shell 208, and adjacent their inner ends which terminate at a location intermediate the inner and outer boundaries of the compressor at about the midpoint therebetween, the blades are fixedly secured to a generally cylindrical inner support 214 which extends between and is supported by the outer sidewall 215 of the compressor and inner divider wall 216 thereof, as shown in FIG. 13. It will be evident that the support 214 is necessarily provided with a plurality of spaced apart inlet ports 217 therealong in respective communication with the inlet passages 212. It will be clear then that the stator of the compressor 39 has a plurality of angularly spaced flow inlet systems each comprising an inlet opening 207, inlet passage 212 defined between two successive stator blades 211, and an inlet port 217 formed in the support 214, and that successive inlet systems are spaced from each other.

Located within the annular compression chamber 218 defined within the cylindrical support 214 is an intake rotor comprising a plurality of angularly spaced blades 219 secured at the inner roots thereof to a hub 220 mounted upon the sleeve 41 so as to rotate therewith by means of a plurality of spiders or transverse walls 221. The blades 219 each extend outwardly from the hub 220 and forwardly with respect thereto or in the direction of rotation, as indicated by the directional arrow in FIG. 14. In cross section, the blades have the usual arcuate form and are concave along the leading side thereof, as is shown in FIG. 14. Accordingly, as the rotor assembly comprising the blades 219 is rotated in a clockwise direction (as viewed in FIG. 14), air is drawn inwardly through each

inlet system comprising the aforementioned inlet openings 207, inlet passages 212, and inlet ports 217, and is elevated somewhat in pressure within the annulus 218 and is ejected therefrom into the discharge section of the compressor 39 which will now be described.

The discharge section of the compressor 39 is shown most clearly in FIG. 15, and it includes a plurality of blades 222 having the root ends thereof secured to the aforementioned hub 220. The blades 222 are angularly spaced about the hub and extend radially outwardly therefrom, projecting to a greater radial length than the aforementioned blades 219. Each of the blades 222 has a compound curvature twisting outwardly and forwardly along the side thereof remote from the inner blades 219 so as to receive air spilling axially therefrom, collect the same, and accelerate it radially. The blades 219, it may be noted, curve forwardly along their inner edge portions remote from the outer blades 222 so as to facilitate the axial spillage of air thereto. The mass of air thus accepted from the blades 219 is discharged centrifugally by the blades 222 through outlet openings 225 provided for this purpose in the outwardly extending lateral flange of the aforementioned divider wall 216, in the inwardly extending annular flange 227 of the outer casing wall 218 of the compressor, and in the inner wall of the annular casing component defining the collection space 210.

It will be apparent that the compressors 39 and 39' are substantially identical and that in any engine apparatus having only a single combustion assembly only one compressor would be used. In view of the duality of the compressors in the engine apparatus 20, the inner blades 219 are disposed within a common compression chamber 218 since this simplifies the construction somewhat although a divider wall therebetween can be included should this be desirable for any reason. As the rotor components of the compressors 39 and 39' are rotatably driven because of their connection with the turbines 40 and 40' via the sleeve 41, atmospheric air is drawn inwardly into each compressor through the openings 204, 205 and 206 in the shell 63, housing 21, and casing 30 and through the various inlet systems defined by the inlet openings 207, inlet passages 212, and inlet ports 217. This inward flow of air is depicted in FIG. 13 by the various arrow-equipped flow lines provided for this purpose, and inwardly flowing atmospheric air is drawn radially by the blades 219 and is forced thereby into the outer blades 222 which forces the air radially outwardly through the various discharge openings 225 and into the collection space 210. At this time, the atmospheric air has been compressed or elevated in pressure and is delivered to the respective combustion assemblies 32 and 32' via the conduits 209 and 209'.

It will be apparent that as the inner blades 219 are rotatably displaced relative to the stator section and blades 211 thereof, each blade 219 traverses an inlet port 217 to receive atmospheric air therefrom and immediately thereafter traverses a closed segment of the inner support 214, at which time the air is transferred to the adjacent blade 222 so as to prepare the blade 219 (and pocket defined thereby) for a further charge of atmospheric air as the blade traverses a successive inlet port 217. Analogously, each charge of air received within a pocket defined by a blade 222 is accelerated

radially outwardly therealong, and is then expelled with substantial kinetic energy into the space 210 through a discharge opening 225 as each blade 222 is alternately traversing an opening 225 and a solid seal component defined by the flange 227 intermediate successive discharge openings.

In view of the rather large number of compressor blades 219 and 222, a substantially constant volume, uniform pressure air mass is collected within the collection space 210 for any particular velocity of the compressor rotors. As previously explained, however, the output of the compressors 39 is automatically tailored to the requirements of the combustion assemblies 32 since the compressors are driven by the exhaust outputs of the combustion assemblies via the turbines 40. Accordingly, as the firing rate of the piston-cylinder structures within each combustion assembly is decreased and/or the stroke length of each piston 36 is decreased, the requirement for air for combustion from the compressors 39 diminishes accordingly but so does the output of the compressors since such output thereof is directly related to the volume of the combustion gases being discharged by the combustion assemblies and which discharge, necessarily, decreases along with stroke length and firing rate. The converse is true so that as the power demands of each combustion assembly increase (i.e., the firing rate and/or stroke length of each piston 36 increases), the compressors 39 provide a greater supply of supercharged air for combustion to the combustion assemblies because they are rotatably driven at a higher rate by the turbines 40 as the consequence of the greater supply of exhaust gases delivered thereto.

Various components of the engine apparatus 20 are water-cooled, and the water-cooling system which will now be described is shown in FIGS. 17 and 18, to which particular reference will now be made.

The main shaft 25 of the engine apparatus is hollow or has a longitudinally extending passage centrally disposed therein throughout substantially its entire length, and such flow passage (denoted with the numeral 228 in FIGS. 16 and 18) is adapted to be connected to a suitable supply of cooling liquid, usually water, which may be delivered thereto such as from the bottom or outlet conduit of the usual automobile radiator (not shown). In FIG. 18, the diagrammatic indication of the cooling passage 228 is designated with the same numeral. Within the interior of the engine apparatus and generally adjacent the combustion assemblies 32 and 32', the supply passage 228 is connected by branch conduits with the aforementioned flow tubes 172 (see FIGS. 3 and 4) disposed within the cooling chambers 165 and with the cooling jackets 174 by means of which heat is extracted from each of the cylinders 34. Such interconnection of the supply passage 228 with the cooling tubes 172 and cooling jackets 174 is diagrammatically depicted in FIG. 18 and in structural terms is accomplished in any conventional manner taking into account any requirement for relative rotation such as between the shaft 25 and any components associated therewith such as the housing 229 shown in rotative association with the shaft in FIG. 16 (the combustion assemblies 32 and 32' being constrained on the main shaft so as to rotate therewith).

The supply passage 228 also supplies a flow of water about the cooling chamber 200 and tailpipe 201 and this arrangement is diagrammatically shown in FIGS. 17 and 18, it being understood that suitable heat exchanger conduits of conventional construction and design will be provided for this purpose. In FIG. 17, the tailpipe 201 is shown to have an inner chamber or annulus 230 disposed in circumjacent relation therewith which receives cooling liquid from the passage 228 and then delivers such fluid to an outer chamber or annulus 231 which communicates with a return passage 232 defined between inner and outer shaft elements 234 and 235 that together comprise the main shaft 25. The return passage 232 generally parallels the supply passage 228 and may be connected to the upper or hot water return connection of a radiator for an automotive vehicle.

The described liquid-cooling system may be a closed and pressurized system and may use any suitable liquid coolant such as water, glycol, mixtures thereof, etc., and it functions to cool both the air cooling chambers 165 in each of the combustion assemblies 32 and the piston-cylinder structures 36,34 located within such assemblies. Additionally, the system cools the exhaust gases being dissipated to atmosphere via the tailpipe 201, and in cooling such gases dissipates a substantial portion of the noise-creating thermal energy ordinarily present in hot exhaust gases and also causes collection 30 of pollutants present in the exhaust gases within the chamber 200 which can then be cleaned periodically so as to dispose of the materials collecting therewith.

The power take-off or delivery components of the engine apparatus have been previously described in 35 terms of their essential function with reference to FIG. 1. Further illustrative elaboration concerning the same is shown in FIG. 16 and brief consideration will now be given thereto.

The transfer shaft 24 is drivingly connected to the 40 power output shaft 26 via the gears 27 and 28, and the output shaft 26 may be equipped with a gear 236 representative of a driving connection thereto which, for example, may be the input gear to a power transmission. The shafts 24 and 26 are journaled in bearings, as 45 illustrated, and the direction of rotation of the output shaft 26 will depend upon the direction of rotation of the shaft 24 as defined by the coupling thereto of the aforementioned forward and rearward clutches 58 and 59, as previously explained. It will be recalled that the forward clutch 58 has the input section 60 thereof connected with the main rotary of the engine so as to be rotatably driven thereby, and when the output section 61 of the clutch is drivingly connected with the input section thereof, the output shaft 26 is rotated in one particular direction.

Analogously, when the forward clutch 58 is disengaged and the rearward clutch 59 engaged, the input section 62 of the rearward clutch drivingly engages the 60 output section 64 which is then connected through the gears 27 and 28 with the output shaft 26 so as to rotate the same in a direction corresponding to the direction of rotation of the cam track casing 30. The input section 62 of the rearward clutch 59 is drivingly connected by a spider plate 237 and casing extension 238 to the cam track casing 30 and cam assemblies 31 and 31', thereby causing the casing 30 to drive the input section

62 of the rearward clutch. The hydraulic turbine 51a and interconnection thereof with the stationary housing 21 and with the adjacent end portion of the shaft 25 are also shown in FIG. 16; and as previously explained, it is useful in loading the shaft especially during reverse drive modes of operation.

The clutches 58 and 59 are conventional fluid clutches energized and de-energized by application of the usual control and circuitry therefor. A variety of suitable clutch mechanisms can be used, and a specific example thereof is a Borg-Warner hydraulic clutch.

The form of the engine apparatus 20 heretofore described and generally illustrated in FIG. 1 includes as components thereof one or more turbines 40 drivingly related to a compressor 39 so as to energize the same, thereby causing atmospheric air to be drawn into the engine apparatus, elevated in pressure by the compressor, and expressed therefrom for delivery to the associated combustion assembly 35. A modification of the turbine and compressor composition is illustrated in FIG. 19 and is generally illustrated thereat with the numeral 240. The module 240 may be taken to be a propulsion turbine operative to derive kinetic energy from the combustion gases delivered thereto via the aforementioned collection conduits 97 (see FIG. 17) and convert such energy into torque delivered to the main engine shaft, the shaft being indicated in FIG. 19 with the numeral 25'. The propulsion turbine 240 does not drive a separate compressor, as in the case of the turbine heretofore described, and if compressed air is to be delivered to the combustion assemblies 32, separate compressor assemblies must be provided for this purpose. Otherwise, the combustion assemblies 32 will be supplied with air for combustion by having atmospheric air supplied directly to the pumping chambers 162.

The propulsion turbine 240 includes an outer shell or casing 241 having an end wall 242 provided with a plurality of apertures 244 through which combustion gases delivered to the turbine by the conduits 97' are injected into the interior of the housing via enlarged defusers 245 provided for this purpose. The outer shell 241 is adapted to be connected to the associated combustion assembly 32 so as to rotate therewith, as previously explained with reference to the turbine 40, thereby obviating the requirement for complex seals between relatively movable components that are rotated at high velocities. Accordingly, the casing or shell 241 is rotatably supported with respect to the main shaft 25' as by means of a bearing assembly 246 rotatably inter-relating the same.

The shell 241 is axially elongated, and adjacent the end wall 242 it is equipped with a rotor 247 comprising a hub 248 keyed or otherwise secured to the shaft 25' so as to rotate therewith, and a plurality of blades 249 that are radially disposed in spaced apart relation and have the root ends thereof anchored in the hub 248 so as to rotate therewith. The blades 249 are axially extending but are turned laterally at their inner end portions, as shown at 250, so that the hot exhaust gases impinging against the blades imparts rotational movement to the rotor 247 and shaft 25' in the direction of the arrow in FIG. 19.

Adjacent its opposite end, the casing 241 is equipped with an end wall rotatably supported by the shaft 25'

through bearing structure (not shown). The end wall 251 is spaced a substantial distance from the inner end portions 250 of the blades 249, and extending inwardly in an axial direction from the end wall 251 are a plurality of partitions 252 that are radially disposed with respect to the axis of rotation of the shaft 25' and are angularly spaced from each other. The end wall 251 and positions 252 comprise with the casing 241 the "stator" component of the turbine 240, and the partitions 252 subdivide the stator end portion of the turbine into a plurality of turning compartments 254 in which air directed thereto after flowing through the blades 249 is reversed in direction and returned to the blades so as to control or limit the maximum angular velocity of the rotor 247.

In this respect, each of the compartments 254 is closed by the casing 241, end wall 251 thereof, successive partitions 252, and the shaft 25' passing through 20 the stator. The inner end of each compartment 254 is open, however, so as to permit ingress of air thereinto and egress of air therefrom. The center portion of each compartment 254 is closed along the inner end thereof by a wedge-shaped filler or wall segment 255 that extends from proximity to the shaft 25' to the outer cylindrical wall of the casing 240 and is rigidly connected therewith. The filler 255 has a shorter angular dimension than the compartment 254 and is generally centered with respect thereto so as to provide a relatively 25 large flow passage intermediate each end of the filler and the partition 252 adjacent the same. One such passage defines the inlet into the compartment 254, and the inlet may be equipped with a plurality of blades or vanes 256 that are generally parallel to the partitions 252 and are spaced apart so as to direct the flow of air leaving the stator blades 249 into the compartment. The other such passage forms the outlet for the compartment 254, and it is similarly provided with a plurality 30 of vanes or blades 257 oriented in general opposition to the direction of rotation of the blades 249 so as to direct air thereagainst in a counter-direction rotation so as to limit the angular velocity of the rotor 247. The blades 257 also extend radially outwardly from the 35 general vicinity of the shaft 25' to the cylindrical wall of the casing 241 and are fixedly secured to the latter. After re-entering the pockets or spaces defined between the stator blades 249, the gases are discharged from the propulsion turbine 240 via a plurality of outlet or exhaust openings 258 formed in the cylindrical wall of the casing 241 at angularly spaced locations thereabout.

In operation of the propulsion turbine 240, hot exhaust gases are directed against the rotor blades 249 from the collection conduits 97', and the energy contained in such hot combustion gases is used to impart rotation to the rotor 247 in the direction of the arrow, as previously explained. As the partially spent gases leave the rotor blades 249, they engage the director vanes 256 at the inlet opening of an adjacent compartment 254 and are turned laterally within such compartment so as to flow intermediate the end wall 254 thereof and filler 255, as indicated by the flow arrows in FIG. 19. The gases continue to be turned in direction until they have described a 180° path of travel and are again axially directed so as to re-enter the rotor 247. The gases re-entering the rotor are angled so as to im-

pede the angular displacement of the rotor 247 and thereby limit the velocity thereof. The gases then leave the rotor 247 through the outlet openings 258 from which they are returned to the exhaust collection chamber 198 through the exhaust conduits 197 (see FIG. 17).

As is well known, the energizing gases may be delivered so as to impart rotation to the rotor 247 in a variety of arrangements and, for example, the conduits 97' and defusers 245 can be disposed and oriented with respect to the end wall 242 and compartments 254 so as to cause the gases leaving the rotor 247 to enter the compartment 254 through vanes 257, and to leave the compartment via the vanes 256. In such an arrangement, the partially spent gases re-entering the rotor 247 from the compartments 254 will function to partially inhibit or limit rotation of the rotor and thereby prevent runaway operating conditions. The various vanes 257, and/or the vanes 256, can be made selectively adjustable so that the degree of rotational inhibition imparted to the rotor 247 by the re-entering gases can be adjusted to meet varying load conditions. All such arrangements are well known in the art and need not be further considered.

The engine apparatus 20 may be designed to include as many automatic controls as desired, or it may be operated almost entirely in response to manual manipulation of control devices provided for this purpose. As respects automatic operation and control, standard fluid turbines, clutches, valves, pressure regulators, etc. may be used in accordance with conventional practice and technology. For purposes of descriptive completeness, a schematic diagram is presented in FIG. 20 which generally depicts fluid delivery to and from various of the functional components referred to hereinbefore, but this figure is not intended to serve as a functional schematic flow diagram since the details necessarily included in a diagram of such type may be conventional, they are well known in the art, and do not contribute to a specific understanding of the present invention. With this preface, attention will now be directed in particular to FIG. 20.

The flow system illustrated in FIG. 20 includes two hydraulic systems that are functionally interrelated: one such system being an oil system; and the second being a fuel system. Such an arrangement is most suitable to an engine apparatus in which relatively low grade fuels are employed (diesel fuels, for example), and it should be understood that another oil system may be substituted for the fuel system shown since the primary purpose of using fuel as one of the control liquids is the desirability of having at least two liquids at different supply pressures. The oil system includes a storage tank or reservoir 259 for oil which has an inlet connected with a sump 260 located within the outer housing 21 adjacent the bottom thereof so as to pick up oil delivered thereto in a manner described hereinafter. The reservoir 259 is also connected to an electrically operated pump 261 that delivers its output to a line 262 one branch of which connects with the main control valve assembly 264 and another branch of which connects with a reverse control valve assembly 265 via a pressure regulator valve 266. Similar pressure regulator valves 267 and 268 connect the conduit 262 with the main valve assembly 264.

In a somewhat analogous manner, the second hydraulic fluid system (i.e., the fuel system in the engine embodiment being considered) includes a tank or reservoir 269 from which fluid is delivered via a delivery line 270 to a pump 271 which may be electrically operated. The pump 271 supplies through a line 272 a valve assembly that includes a high pressure regulator 274 and a low pressure regulator 275. The regulators 274 and 275 are each connected to a control or transfer valve 276 that determines which of the two fluid pressures are directed into the system. At least under certain operating conditions, fuel is returned to the tank or reservoir 269 through a return line 277 connected therewith.

The control valve assemblies 264 and 265 are analogous to the usual gear-shifting mechanism provided in an automotive vehicle to control the forward and reverse operating modes thereof. Each such valve assembly has conventional characteristics and includes various spools, openings, segments, etc. which selectively interconnect and disconnect certain flow paths depending upon the position of the movable valve element, all is well known in the art. Control over the valve assemblies 264 and 265 is suggested by the rods 278 and 279 respectively associated therewith, and which may be taken to be manually manipulatable. Accordingly, interconnection between the assemblies 264 and 265 with the various clutches, turbines, etc. depends upon the location of the control rods 278 and 279, and FIG. 20 depicts the flow connections between these assemblies and the various elements in the system, substantially all of which have been referred to hereinbefore and appropriately provided with reference numerals. Prior to noting certain of these elements, it may be observed that in FIG. 20 each of the two operating engine systems (i.e., the cam assembly 31, combustion assembly 32, compressor 39, and turbine 40; and the cam assembly 31', combustion assembly 32', compressor 39', and turbine 40') are treated as an integer so that only two duplicate components are shown and they are identified with the same numeral one of which is primed, all in identical correspondence with the reference system followed throughout.

Thus, the aforementioned brake mechanism 55 is connected with the main control valve assembly 264 through a line 280 and it is also connected with the reverse assembly 265 through a line 281. The aforementioned turbine or clutch 51 used in association with the gear train 45 is connected with the assembly 264 through lines 282 and 284; one side of the cam control cylinders 194 and 194' are connected through a line 285 having a pressure control valve 286 included therein; the stroke regulator devices 93 and 93' are connected with the assembly 264 through a line 287; and the hydraulic clutches 58 and 59 are respectively connected with the assembly 265 via conduits 288, 289 and 290, 291 (it being appreciated that both of the clutches will be de-energized in the neutral position of the assemblies 264 and 265, and that the forward clutch assembly 58 can be controlled by the assembly 265 since it is always engaged except when the vehicle is in neutral and when the vehicle is in a reverse operating mode in which the clutch 59 is energized). Returning to the override control cylinders 194 and 194', the

opposite sides thereof are connected with the assembly 264 through a flow line 292. For purposes of indicating the interrelationship of the two sides of each such control cylinder 194 and 194', they are respectively grouped by brackets.

Also included in the arrangement shown are air regulators 294 and 294' which are used to limit the pressure developed within the combustion assemblies during short-stroke operation of the engine apparatus. The pressure regulators 294 and 294' are connected along a line 295 which delivers oil to one side of the aforementioned control assemblies 156 and 156' and is connected through a dump valve assembly 296 with the aforementioned flow line 287. The dump valve assembly 296 actually comprises two separate dump valve arrangements one of which is for fuel and the other for the control oil. The dump valve assembly 296 is located generally at the edge of the main rotary and has separate lines 297 and 298 that respectively carry fuel and oil to the ends of the main rotary generally along the center thereof from which the oil is returned to the sump 260 and fuel is returned to the tank 269 (the latter connection thereto not being shown). Regulators 299 and 299' which are used on short stroke operation are connected with a fuel line 300 which couples these devices with the exchange valve 276. The line 300, it will be noted, also connects with the dump valve assembly 296, thereby enabling such valve assembly to rapidly relieve fuel from the line 300 whenever necessary. The aforementioned fuel return line 277 which connects with the fuel reservoir 269 also connects with the devices 299 and 299' so that excess fuel is returned to the reservoir. The fuel line 300 is also connected with a throttle control for the fuel injection system, and the control 301 is used only with certain types of ejectors (the General Motors Corporation fuel injectors for diesel engines), and functions to hold the throttle open until the pressure is relieved at which time the throttle is closed by spring force.

The two control valve assemblies 264 and 265 are interconnected by a flow line 302, and the transfer valve 276 has oil returned therefrom to the assembly 264 via the aforementioned line 287 with which it connects. The condition of the valve 276 determines whether high pressure or low pressure fuel is transferred or delivered thereto to the fuel line 300, and oil to the dump valve assembly 296 is delivered thereto via a line 304 which also connects with one side of the control cylinders 134 and also to one side of the control devices 156. The brake mechanism 44 operative between the stationary outer housing 21 and the cam track casing 30 is connected directly with the control valve assembly 264 so as to be energized in response to control positioning thereof.

The functioning of the system illustrated in FIG. 20 will be apparent from the foregoing description taken together with the prior explanations of the components and their functional interrelationships. In this reference, the various control devices are manipulated in the appropriate manner by delivering control fluids thereto at proper pressures and at appropriate times. For the most part, the appropriate control response is obtained by manipulation of the rods 278 and 279 except for those components which function automatically. In this latter category are the various pressure

regulator valves including the valve 286 which may be responsive to the velocity of the main rotary of the engine to limit pressures along the line 285. The dump valve 296 quickly relieves liquid pressures to enable the engine to be shut down very rapidly. Different fuel pressures are required as between high speed and low speed engine operation, and the regulators 274 and 275 together with the transfer valve 276 provide therefor. The reason therefor involves the centrifugal forces that increase rapidly with engine velocity, and at high engine velocities lower fuel pressures are required and at lower engine velocities higher fuel pressures are needed. It will be appreciated that the centrifugal force which is at greater magnitude as the engine velocity increases could cause flooding and wastage of fuel at high engine velocities when the firing rate of the engine apparatus is relatively low, all as has been previously explained. The dump valve assembly 296 is also arranged with a centrifugal governer to control and limit engine velocity, and as previously noted, it dumps both oil and fuel whenever the set velocity is exceeded.

The oil supply may be used to increase the operating speed of the engine by supplying more fuel thereto, and this will be accomplished by increasing the oil pressure to the ejector control devices 134 and 156 for the exhaust valve and fuel systems. The fuel pressures may then be used to reduce the operating velocities, and generally stated the cooperative interrelationship of the oil pressure, fuel pressure, and centrifugal components 127 associated with the control devices makes accurate regulation thereof readily attainable.

In way of summary, a number of general comments and observations will be set forth. In this reference, the pumping action of the crank arms 90 and pumping elements 161 thereof with the chambers 162 provides a cushioning action as respects the engagement of the follower drivers 182 against the cam plates 179 and 180, thereby tending to reduce wear on both the cam and followers. Ordinarily, centrifugal force holds the followers 182 into tight engagement with the cam surfaces, but if necessary in any particular embodiment of the invention, the followers may be held in engagement with the cam surfaces by suitable biasing members including torsion springs associated with the torsion bars 92. As respects starting of the engine, the stroke regulator and actuator elements 111 can be held by their respectively associated controls 134 so that the exhaust valves remain substantially closed until the pressure within the combustion chambers is sufficiently great to permit the engine to start, it being apparent that the pressure will build up as the velocity is increased by any suitable starter arranged therewith.

Centrifugal force associated with the rotating components of the engine apparatus will cause oil to be thrown outwardly and collected along the outer shell via the sump 260, as previously explained. The engine apparatus 20 is exceedingly easy to maintain because it lends itself to quick assembly and disassembly and tends to be constructed in units or modules so that entire units may be substituted for any that do not function properly. It will be apparent that balance is an important item in a rotational device of the type being considered, so that any such substituted modules will be prebalanced and substituted as an integer. Various arrangements can be employed to hold the engine ap-

paratus together, and as previously explained, the modules may move longitudinally along the central shaft 25 which may serve as a tie shaft, and standard Morris-type tapers may be used to positively position the various interconnected modules at their proper locations. Further access openings may be provided along the outer stationary housing 21 and within the inner casing members so as to permit access into the interior of the engine for adjustment and repair by this technique.

Considering the power transfer unit illustrated in FIG. 19, a further pressure reduction can be provided within the various chambers 254 by cooling the gases flowing therethrough which, evidently, will decrease the volume of such gases and thereby reduce the pressure thereof. The turbine 51 provides a load on the sun gear 47 that resists rotation thereof, and other loading techniques may be used. For example, the sun gear could be loaded by associating it with an electrical device of some sort such as a generator, thereby causing electricity to be generated by rotation of the gear but, at the same time, free rotation of the gear will be restricted.

Any suitable ignition system may be employed for the engine apparatus including one using a glow plug and also one using an electronic energizer since timing mechanisms are essentially unnecessary because of the fuel injection arrangement shown. Very small piston-cylinder structure is required because of the relatively high velocities at which the engine components rotate, and in any case the rotating components provide a built-in flywheel for the engine apparatus. The engine is especially suitable for using non-leaded fuels because it provides time for the fuel to burn completely and thereby obviates the usual requirement for highly volatile leaded fuels.

In the particular engine apparatus being considered which has six piston-cylinder structures distributed in two assemblies 32 and 32', the firing order thereof is counterrotative which contributes to the smoothness with which the engine functions. It will be appreciated that the engine is susceptible of producing greater power at long or complete piston stroke, but the short stroke operation can be desirable, especially during hot weather, because it reduces engine heat especially in the cylinder walls. Although centrifugal force limits the velocity at which any particular engine apparatus can rotate referenced to the structural characteristics thereof, it is used advantageously in the engine apparatus in a number of instances and, for example, it is used as a aid in closing the exhaust valves of the engine, for operating centrifugal control devices, for operation of the components 111, etc. Centrifugal force also holds the cam followers in engagement with the cam surface, as previously explained, and where desired, hydraulic assistance may be employed for relieving the magnitude of the force urging the followers outwardly into tight engagement with the cam surfaces which, evidently, will tend to reduce cam wear. Hydraulic pressure systems may also be used for manipulating the various rocker arms 101 and 144 rather than the systems shown.

The engine apparatus is able to produce tremendously high torque at low RPM's because of the driving interconnection defined between the two rotating com-

ponents (the main rotary and cam track casing) via the planetary gear train 45. Because of this driving interconnection, the torque that the engine is capable of developing is very great.

As previously explained, the engine apparatus is more efficient than conventional engines for a variety of reasons including improved charging and purging of the combustion chambers, the longer time afforded for fuel burning because the engine can fire at a low repetition rate during high engine velocities, and the higher compression ratios that characterize the engine apparatus. The improved efficiency, it will be apparent, significantly reduces fuel consumption and reduces air pollutants otherwise attributable thereto. The relatively long lever arms through which the piston force operates also enables the engine to develop greater output torque for a given fuel charge. The engine also runs quite cool because of the straight-line flow through each combustion chamber from the inner to the outer end thereof and relatively large volume of air passing through each chamber, each of which tends to cool the same. As a result of its efficiency, a lightweight and small engine has a high horsepower output, thereby significantly increasing the horsepower to weight ratio available in conventional engines. As previously explained, not only is the engine itself small and lightweight for any given horsepower development but the overall drive train is further reduced in weight because of the omission of the usual transmission that results from the ability of the engine to operate interchangeably and quickly between forward and reverse modes.

Generally stated, the engine apparatus may use different types of power-creating arrangements rather than the piston-cylinder structures and driving interconnections thereof shown as long as two relatively rotating components are provided and driven, are susceptible of being loaded or of having loads applied thereto such that one such component can be made to deliver output power in preference to the other, and so long as these components are drivingly interconnected by the planetary gear train and associated mechanism so that the two components can be made to rotate in the same direction when desirable.

While in the foregoing specification an embodiment of the invention has been set forth in considerable detail for purposes of making a complete disclosure thereof, it will be apparent to those skilled in the art that numerous changes may be made in such details without departing from the spirit and principles of the invention.

What is claimed is:

1. Rotary engine apparatus of the character described, comprising a plurality of relatively rotatable components at least one of which is operative to produce output power, a casing defining a cylinder therein equipped with a reciprocable piston adapted to compress a combustible admixture of fuel and air and derive energy from combustion thereof to energize the power stroke of said piston, means drivingly interconnecting said cylinder casing and piston, respectively, with at least two of said relatively rotatable components so as to develop torque therebetween in response to the power stroke of said piston and thereby enforce relative rotation upon said two components,

and rotation-regulating means operatively connected with at least one of said pair of relatively rotatable components so as to enforce a greater rotational movement upon the other in response to power development between said cylinder casing and piston.

2. The engine apparatus of claim 1 in which said rotation-regulating means includes rotation-inhibiting mechanism operative to inhibit free rotation of one of said pair of rotatable components.

3. The engine apparatus of claim 1 in which said rotation-regulating means includes a selectively operable gear train adapted to drivingly interconnect said pair of rotatable components to effect concurrent rotation of each in the same direction at different angular velocities.

4. The engine apparatus of claim 1 in which said rotation-regulating means includes rotation-inhibiting mechanism selectively operative to inhibit rotation of one or the other of said pair of rotatable components, thereby enabling torque to be selectively produced by said engine apparatus in opposite angular directions.

5. The engine apparatus of claim 1 in which said means drivingly interconnecting said pair of relatively rotatable components and said cylinder casing and piston include cam structure connected with one of said pair of rotatable components so as to drivingly couple the same, connector structure coupling said cylinder casing with the other of said rotatable components comprising said pair thereof, and power-developing cam follower structure operatively connected with said piston and effective in response to reciprocable displacements thereof to drivingly engage said cam structure and develop torque therewith operative to enforce relative rotation upon said rotatable components.

6. The engine apparatus of claim 5 in which said cam structure is adjustable so that the magnitude of the rise and fall thereof can be changed to vary the stroke length of said piston, and in which means are included for selectively adjusting said cam structure.

7. The engine apparatus of claim 5 in which said power-developing cam follower structure includes a torsion bar and crank assembly interconnecting the same with said piston so that the reciprocable displacements of the latter are converted into angular displacements of said torsion bar, and further includes a cam follower connected with said torsion bar so as to be an-

gularly displaced thereby, said cam follower being in engagement with said cam structure so as to develop driving force effective thereupon in response to reciprocable displacements of said piston and corresponding angular displacements of said torsion bar.

8. The engine apparatus of claim 7 in which said cam structure is adjustable so that the magnitude of the rise and fall thereof can be changed to vary the stroke length of said piston, and in which means are included for selectively adjusting said cam structure.

9. The engine apparatus of claim 1 in which said cylinder casing is equipped with exhaust port structure and valve mechanism controlling the same, in which said piston is equipped with inlet port structure for air 15 and valve mechanism controlling the same, and further comprising pump mechanism operative in timed relation with the reciprocable displacements of said piston so as to develop a charge of compressed air expressed through said cylinder via said exhaust and inlet port structures to purge said cylinder and to provide air for combustion, and means for energizing said valve mechanisms in timed relation with the reciprocable displacements of said piston to effect such cylinder purging and supplying of combustion air.

10. The engine apparatus of claim 9 in which said pump mechanism includes a pump element operatively connected with said piston so as to be actuated in mechanically enforced synchronism therewith.

11. The engine apparatus of claim 9 in which said means for manipulating said inlet valve mechanism includes a push rod structure reciprocable generally along the longitudinal axis thereof for opening said inlet valve mechanism, and in which means are included for selectively changing the effective length of said push rod structure and thereby alter the time relationship of the opening and closing of said inlet port structure in its relation to the reciprocable displacements of said piston.

12. The engine apparatus of claim 9 in which said means for manipulating said exhaust valve mechanism includes rocker arm structure and means for cyclically displacing the same to open said exhaust port structure, and in which means are included for selectively changing the displacement of said rocker arm structure so as to change the time relationship of the opening of said exhaust port structure in its relation to the reciprocable displacements of said piston.
